UNITED STATES PATENT OFFICE.

WILLIAM C. STEWART, OF LYNN, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

PULLING-OVER MACHINE.

1,118,965.

Specification of Letters Patent.

Patented Dec. 1, 1914.

Application filed November 14, 1906, Serial No. 343,458. Renewed May 3, 1913. Serial No. 765,395.

To all whom it may concern:

Be it known that I, WILLIAM C. STEWART, a subject of the King of Great Britain, and a resident of Lynn, county of Essex, State 5 of Massachusetts, have invented an Improvement in Pulling-Over Machines, of which the following description, in connection with the accompanying drawings, is a specification, like letters on the drawings 10 representing like parts.

This invention relates to machines for pulling over the uppers of boots and shoes preparatory to the lasting operation.

As pulling over is the first operation going to the final shaping of the upper to the last a high degree of skill must be exercised so that when pulled over, the upper will be properly and evenly positioned upon and correctly drafted over the last. On shoes of 20 different sizes the tip line of the upper is at different distances from the end of the toe, and this distance also varies in different styles of shoes. In pulling over great care must be taken to bring the tip line in proper 25 position to give the correct length of tip for the size and style of shoe being operated upon and especially to place the upper upon the toe portion of the last, so that after it has been secured in position the tip line 30 will be properly alined across the shoe as it is viewed by the wearer.

In preparing the shoe for the pulling over operation the upper is assembled about the last, preferably after the insole has been 35 applied, and it may be, tacked thereto, and usually the upper materials at the heel are temporarily secured against displacement on the last by a single fastener driven therethrough and into the last, leaving the edges 40 of the upper and parts within it extending loosely about the last. The upper and linings, box toe, heel stiffener and other parts within it will hereinafter, for convenience, be referred to simply as the "upper."

45 Prior to my invention, in pulling over by hand, it has been customary for the operative to jack the assembled shoe sole uppermost and then by the use of ordinary hand lasting pincers draw the upper stock, linings and box toe down over the toe of the last and over the sole and to tack the upper to the insole at substantially the center of the tip of the toe. While the upper is being 50 thus drafted forwardly at the toe, the oper-

ator maintains the middle finger of his left 55 hand in touch with the tip line of the upper and attempts by sense of touch alone, to pull the upper so that the tip line will be properly positioned across the last. He then seizes the upper stock, linings and box 60 toe at one side of the toe, sometimes slightly forward of the tip-line, and drafts said side forwardly and upwardly over the insole where it is tacked usually with two tacks, one on each side of the tip line. The other 65 side is then pulled over and tacked in a similar manner. During these latter operations the operative continues to use the sense of touch alone to determine the position of the tip line upon the last. Frequently after 70 the shoe is taken off the jack and turned over for inspection some or all of the tacks have to be withdrawn and the upper again pulled over to draft the upper stock properly and position the upper correctly upon 75 the last.

Attempts have been made heretofore to improve upon the hand method of pulling over by providing a machine to initiate and closely follow the character and sequence of 80 steps in the hand method, but such prior attempts have not completely satisfied the requirements of pulling over, as well understood by those skilled in the art.

With these general considerations in view 85 one of the objects of the present invention is to provide a machine for pulling over the uppers of boots and shoes, wherein the mechanical principles and operations in some respects depart from and in others are improvements upon the prior hand and machine methods and the upper is properly drafted and positioned with respect to the last without objectionable features incident to each. 95

The invention consists of the features, and mechanical devices and combinations hereinafter disclosed and described and then definitely pointed out in the claims.

In the accompanying drawings which 100 have been provided to show only one of the many forms contemplated as embodiments of the invention, Figure 1 alone shows the head of the machine at an angle to the horizontal, as arranged in practice, all the other 105 figures being placed "square" on the sheets for convenience of delineation and explanation.

Fig. 1 is a side elevation of the machine with the base of the frame broken away to show the parts within it, and with the guides for the pulling over means in dotted outline only to simplify the drawing; Fig. 2 is a plan view looking in the direction of the arrow *a*, Fig. 1; Fig. 3 is a side elevation of the head of the machine with the guides for the pulling over means shown in dotted outline only to simplify the drawing; Fig. 4 is a vertical longitudinal section of the head of the machine on line 4—4 of Fig. 2 with the pulling over means broken away to simplify the drawing; Fig. 5 is a detail plan of the rear portion of the machine showing the grippers as they are positioned before seizing the upper, with the fastener supplying mechanism removed in order to show the parts therebeneath; Fig. 6 is a horizontal section on line 6—6 of Fig. 4; Fig. 7 is a horizontal section on line 7—7 of Fig. 4; Fig. 8 is a transverse section on line 8—8 of Fig. 1, looking in the direction of the arrow *b*, with the last removed; Fig. 9 is a transverse section of the mechanism below the head of the machine on line 9—9 of Fig. 1, looking in the direction of the arrow *c*; Fig. 10 is a longitudinal section of the mechanism below the machine head on line 10—10 of Fig. 7; Fig. 11 is a detail front elevation of a portion of the mechanism below the machine head; Fig. 12 is a plan of Fig. 11; Fig. 13 is a detail of a part of a mechanism shown in Figs. 11 and 12; Figs. 14 and 15 are perspective views, partly in section, of the guides and slides at the rear of the machine and their supports; Fig. 16 is a perspective view of the curved guide for the toe grippers and its support; Fig. 17 is a detail side elevation of the toe pulling over means including its support and the fastener supplying and inserting mechanism, with the grippers open; Fig. 18 is a front elevation of Fig. 17, omitting the last; Fig. 19 is a vertical section of the toe pulling over means on line 19—19 of Fig. 2; Fig. 20 is a side elevation similar to Fig. 17 with the grippers closed on the upper, and the last moved heelward; Fig. 21 is a rear elevation of Fig. 17, with the push rod omitted; Fig. 22 is a side elevation similar to Fig. 17 showing the grippers and driver moved down the vertical guide with the edge of the upper brought to a position beneath the last edge; Fig. 23 is a side elevation similar to Fig. 17 showing the edge of the upper placed adjacent the insole and a fastener driven therethrough and into the insole; Fig. 24 is a detail side elevation of the side pulling over means including its support and the fastener supplying and inserting mechanism, with the grippers open; Fig. 25 is a right-hand side elevation of Fig. 24, with the push rod omitted; Fig. 26 is a horizontal section on line 26—26 of Fig. 24; Fig. 27 is a transverse section on line 27—27 of Fig. 24; Fig. 28 is a detail side elevation similar to Fig. 24 showing the edge of the upper at the side of the shoe placed adjacent the insole and a fastener driven therethrough and into the insole; Fig. 29 is a detail side elevation of one of the toe gripper carriages and mechanism sustained thereby; Fig. 30 is a right-hand side elevation of Fig. 29; Fig. 31 is a horizontal section on line 31—31 of Fig. 29; Fig. 32 is a detail side elevation partly in section of one of the side gripper carriages and mechanism sustained thereby; Fig. 33 is a right-hand side elevation of Fig. 32; Fig. 34 is a horizontal section on line 34—34 of Fig. 32; Fig. 35 is an elevation of one side of the fastener supplying mechanism; Fig. 36 is an elevation of the other side of the fastener supplying mechanism to that shown in Fig. 35; Fig. 37 is a plan view of Fig. 35; Fig. 38 is a horizontal section on line 38—38 of Fig. 35; Fig. 39 is a left-hand side elevation of Figs. 35 and 36; Fig. 40 is a transverse section on line 40—40 of Fig. 35; Fig. 41 is a detail side elevation of the driver head; Fig. 42 is a front elevation of Fig. 41; Fig. 43 is a detail perspective view of the presenter block; Fig. 44 is a detail vertical section of one of the fastener supplying means showing the relation of the parts before the gripper carriage begins to descend; Fig. 45 is a similar view to Fig. 44 showing the gripper carriage moved downwardly sufficiently to engage the fastener; Fig. 46 is a similar view to Fig. 44 showing the gripper carriage moved sufficiently to enable the driver to withdraw the fastener from the presenter block; Fig. 47 is a similar view to Fig. 44 showing the gripper carriage near the completion of its outward movement or return to starting position; Fig. 48 is a detail plan of the toe gripper jaws; Fig. 49 is a side elevation of Fig. 48 with the jaws open; Fig. 50 is a front end elevation of Fig. 49; Fig. 51 is a detail plan of the side gripper jaws; Fig. 52 is a side elevation of Fig. 51 with the jaws open; Fig. 53 is a front end elevation of Fig. 52; Fig. 54 is a detail plan of the heel support; Fig. 55 is a side elevation of Fig. 54; Fig. 56 is a rear elevation of the heel support, the guide rods being in section; Fig. 57 is a vertical section on line 57—57 of Fig. 56; and Fig. 58 is a diagrammatic view of the bottom of both a right and left last showing their relation when their tip lines are superposed one on the other.

In the embodiment of my invention selected for illustration herein and shown in the drawings, referring more particularly to Figs. 1, 3, 4 and 8, a suitable base 2 sustains a framework 4, forming the head of the machine on which certain operative parts are mounted. The framework forming the

head is preferably mounted (Fig. 1) at an angle of about thirty degrees to the horizontal so that when the shoe to be pulled over is placed thereon it rests with the heel toward the operative, in such a position that he views it about as one would view a shoe upon his own foot. Such a position of the last enables the operative to see clearly and without effort the whole upper portion of the shoe, the position of the upper thereon and particularly the tip line of the upper.

Extending rearwardly from the head 4 is a frame or bracket 6 (Figs. 4, 7, 14 and 15) which sustains a table 8 slidably mounted 15 between longitudinally arranged gibs 10 for a purpose to be hereinafter described. On the table 8 is mounted a curved guide 12 (Fig. 16) which, as shown, is preferably circular, and extends about the toe of the shoe 20 to be lasted (see Figs. 2 and 5). The ends of the guide 12 are supported by resting on arms 6* extending from the bracket 6. On this curved guide 12, and preferably movable therein, are mounted the means for 25 seizing the toe portion of the upper in the operation of pulling over. A little forward of the table 8, and substantially under the ball of the last when the latter is placed in position upon the machine, is arranged a 30 frame 14 (Figs. 4, 6, 7 and 8) extending transversely of the head of the machine and preferably arranged to have movement longitudinally thereof on ways 13 (Fig. 8), said frame supporting at either side of the 35 last the means for seizing the sides of the upper in the pulling over operation.

The head of the machine is also provided, as here shown, with a supporting bracket 16 (Fig. 4) having both forward and rearward 40 extensions at its top. On the rearward extension, which lies substantially under the instep of the last when in place upon the machine, is mounted a block 18 provided with a further rearward extension, preferably 45 in the form of wings 21 (Figs. 4 and 8), upon which the ball of the last is adapted to rest.

On the forward extension of the supporting bracket 16 are preferably formed longitudinal guides 22 (Figs. 2 and 4), which carry between them a block 24 from which projects a standard 26, sustaining a support for the heel of the last. This support may be constructed so as to support, without 50 manual adjustment, any shape of last heel. To this end, referring to Figs. 54 to 57, the preferred construction comprises a block, in the form of a sleeve 28, keyed to the standard 26, which sleeve is provided with one 55 or more longitudinally extending pins 30, as here shown two, slidably mounted in guideways 32 in the sleeve 28 and held rearwardly by means of springs 34, each spring being secured at one end to a lug on its respective 60 pin and at its other end to a lug on the

sleeve. This construction keeps the pins 30 normally in their rearward position. The rear ends of the pins 30 sustain a transverse block 36, forming a frame which supports, by horizontally arranged pivots 38 at each 70 end, a member 40, shaped to form a seat for the bottom and back of the heel of the last. This construction allows the plane of the base of the heel seat to be placed at any desired angle to the horizontal, to suit the style 75 of last being operated upon. The heel seat 40 is also provided at each end with vertically arranged pins 42, upon which are pivoted rearwardly extending arms 44, adapted to engage the sides of the heel portion of a 80 shoe placed upon the seat 40. These side arms are normally yieldingly held against the shoe by means of a spring 46, the ends of which are secured to lugs on the arms 44. Inward movement of these arms 44 under 85 the force of the spring 46 is limited by the engagement of lugs 43 on the arms with lugs 45 on the heel seat 40. In their preferred normal position the arms 44 converge slightly. The arms 44, and with them the 90 heel seat 40 upon which they are mounted, are also yieldingly held upwardly by means of springs 48, extending between lugs on the arms 44 and lugs on the frame 36. This upward movement is limited by the engagement of lugs 47 on the heel seat member 40 with lugs 49 upon the frame 36. In its preferred normal position the plane of the heel seat 40 is substantially at a right angle to the standard 26. In order to avoid marring 95 the surface of the upper, a piece of felt 50, or other soft substance, may be secured in any convenient manner to the inner surface of the back 41 of the heel seat 40 and also, if desired, to the inner surface of the side 100 arms 44. The construction just described allows movement of the side arms independently of the heel for lasts of different width, and also allows a movement of the heel seat carrying the side arms with it for 105 lasts of different styles, that is, for lasts where the curve under the shank from the ball line to the heel seat may be more or less pronounced. Both of these adjustments are 110 yielding and adapt themselves naturally to 115 the heel portion of any last which may be used upon the machine. The entire heel support is also given a vertical adjustment upon its standard 26 which will be described hereinafter in connection with its function. 120

From the construction described it will be apparent that when the last with the upper thereon is placed in the machine, the arms 44 act upon the upper to slidingly shape the counter to the last and hold the 125 parts in such position during the subsequent operations of the machine.

In positioning a last upon the machine the heel thereof is placed upon the seat 40 and between the arms 44 of the heel support, said 130

arms adapting themselves to the curvature of the sides of the heel portion of the last and centering the same upon its seat. At the same time the ball of the last is placed upon the wings 21 of the ball support and to further aid, among other functions in positioning the last in correct position with relation to the pulling over means which surround it, a toe positioning stop 52 (Figs. 4, 5 and 8) and side positioning stops 54 (Figs. 3 and 24) are provided for engaging the last. The toe stop 52 is preferably V-shaped to better center the tip of the toe thereagainst, and is supported upon the toe block 18 and extends rearwardly between the wings 21 and centrally of the ball support, which is recessed to receive it (see Fig. 4). The side stops 54 are preferably mounted upon the supports for the side pulling over means and are shaped to engage the angle formed by the side and bottom of the last. The side positioning stops 54 may be omitted if desired for obviously the V-shaped toe stop 52 and the heel seat 40 will ordinarily be sufficient to locate the last on the ball support both longitudinally and transversely.

A preferred construction for use in the illustrated embodiment of the invention, of the pulling over means at the sides of the last including their supports is shown by Figs. 24 to 28, and as the construction is similar for both sides of the last it will be sufficient to describe only one. Upon the frame 14 is a block 56 provided with a transversely extending guideway 57 (Fig. 27), which sustains an upwardly extending supporting frame 58. This frame 58 is provided with a vertically arranged curved guideway 59, preferably circular. When in its normal position prior to pulling over the upper on a particular size of last the center of the curvature of this guide is preferably substantially in the vertical plane of the last edge or in the plane of the last bottom. In this guide moves a carriage 60, on which is mounted a pair of gripper jaws for seizing and holding the edge of the upper. The carriage 60 is preferably provided with lugs 62 extending inwardly, each of which is provided with a slot 64, the purpose of which will be explained hereinafter. Extending between these lugs and entering the slots is a pin 66 on which the gripper jaws are pivotally mounted. These side grippers, shown in detail in Figs. 51 to 53, are provided with transverse serrations or teeth upon the gripping surfaces of both the upper and lower jaws 61 and 63, respectively, which extend on one side of the pin 66. The rear portions or shanks of the jaws 61 and 63, extending on the other side of the pivot pin, are preferably each bifurcated forming pairs of legs 68 and 70, each pair extending at an angle to the other when the jaws are open, one pair lying between the other pair.

Preferably disposed between the inner pair of legs 70 is a link 72, having on one end a transversely extending pin 74, which pin passes through longitudinally arranged slots 69 and 71 in the pairs of legs 68 and 70, respectively. On moving the link 72 outwardly the pin 74 is drawn outwardly through the slots 69 and 71 simultaneously and this action tends to bring the shanks of the gripper jaws in parallelism, thus moving the jaws about their pivot 66 and closing them. Movement of the pin 74 in the opposite direction will open the jaws. In this embodiment of the invention the preferred mechanism for actuating the link 72 to close the jaws 61, 63 is shown in Figs. 32 to 34. Referring to said figures, on the carriage 60 is pivoted a lever 76, one end of which is pivotally secured to the inner end of a short link 78 (see Fig. 31), the outer end of which short link is pivoted to the outer end of the link 72. Means, as a pin 79, is provided extending from the link 72 across link 78 to prevent movement of the short link about its pivot to link 72 in one direction, and for maintaining the pivots of the link 78 and pin 74 in such position that the pull of the lever 76 will act directly on pin 74. The function of this connection through the link 78 will be hereinafter explained. The other end of lever 76 is provided with a pin 80, loosely mounted therein, and on this pin is secured a pawl 82, adapted to engage with the teeth of a ratchet 84, mounted on the upper end of the carriage 60. Lever 76 is also provided on the other side of its pivotal point from link 72 with an arm 86 projecting outwardly beyond the support 58, preferably having a socketed end 87 adapted to be engaged by a push rod 88. With this construction, assuming that the jaws 61, 63 are open, upward pressure on the push rod 88 will turn the upper end of the lever 76 inwardly about its pivot, thus drawing the pin 74 on link 72 along the slots in the legs of the grippers and closing the jaws, and at the same time locking them in closed position by the engagement of pawl 82 with its ratchet 84. It is convenient to have the gripping surface of the lower jaw 63 extending in a plane substantially parallel to the bottom of the last so that the toe portion of the upper, which when the shoe is assembled extends loosely over the last in substantially a single plane, may be readily positioned between the jaws by the operative and to this end any convenient part on the carriage 60, as the end of the barrel 146 (Fig. 32) hereinafter mentioned, may be used with which the legs 68 engage as the jaws are being opened to prevent the gripping surface of the lower jaw from passing out of the desired plane and causing the greater part or whole of the opening to be performed by movement of the upper jaw.

The preferred form of gripping means for the toe of the last, in the illustrated embodiment of the invention, is shown in Figs. 17 to 23, and it will be noted (see Figs. 2 and 5) that instead of using a single pair of gripper jaws, as has been customary heretofore, I prefer to provide two pairs of gripper jaws arranged adjacently, one on each side of the tip of the toe of the last. As the construction and mounting of both of these pairs of gripper jaws is similar I will describe but one pair. Mounted to slide in the curved guide 12 is an upwardly extending support 90, which sustains a vertically arranged curved guide 92, preferably circular and of the same radius as the curved guides 59 at the sides. In this guide is slidably mounted a carriage 94 (Figs. 29 to 31), similar to the carriage 60 for the side grippers, with the exception that the slots 96 corresponding to the slots 64 in the lugs 62 on the side gripper carriages 60, need not be so long as the slots 64. I preferably provide light springs 99 extending from the gripper carriages to the pins 66 adapted to maintain said pins in the outer ends of the slots 96 so that when the link 72 commences its outward movement there will not be an outward movement of the jaws before they close. The construction of the toe grippers (see Figs. 48 to 50) is similar in all respects to that described for the side grippers, with the exception that instead of being longitudinally serrated for roughening the gripping surfaces of the jaws I prefer to provide their engaging faces with transversely arranged corrugated surfaces 102. As thus constructed and using two pairs of jaws, when the toe grippers are closed upon the upper it is fluted or corrugated radially about its edge and the surplus stock around the toe is thus taken up and the toe portion of the upper distributed evenly around the last, rendering the latter operation of lasting more simple and aiding the appearance of the finished shoe. This corrugating of the upper at the toe is preferably further aided by placing the two pairs of toe grippers in such position on either side of the tip of the toe of the last, before they are closed to grip the upper, that only a sufficient amount of the upper remains between the grippers to form an additional corrugation of the proper relative size. Thus when the grippers are loosened and removed from the upper it is distributed evenly about the toe from a point where the outside edge of one of the toe grippers rested to the point where the outside edge of the other toe gripper rested. The actuating mechanism for closing the toe grippers and locking them in closed position is similar in all respects to that heretofore described for the side grippers, push rods 104 being utilized to actuate said mechanism.

Means similar to that employed for the side grippers, here shown as shoulder's 65 (Figs. 19 and 29), are provided for keeping the gripping surface of the lower jaws 70 of the toe grippers in a plane substantially parallel to the bottom of the last.

It will be noted (see Figs. 18 and 21) that the carriages 94, on which the grippers are mounted, are sustained and guided between side plates which form the curved guideways 92 in which the carriages move, the carriages and actuating mechanism for closing the gripper jaws thus being mounted centrally of the supports 90. This construction allows the toe grippers to be placed closely adjacent each other as is desirable. In the case of the side grippers, however, (see Figs. 25 to 27), it is more convenient to support the carriages 60 in guideways 59, which are formed in one side of the supports 58, as this enables all grippers to be brought nearer together in pulling over the uppers of small shoes. Obviously, however, all grippers may be mounted alike if it is found desirable to do so. As illustrated, the side gripper carriages are provided with T-projections 60^x (Figs. 33 and 34) on one side adapted to fit in the guides 59, and the toe gripper carriages are formed of channel plates which embrace the guides 92. The toe gripper carriages are further sustained upon their guides 92 by hooks 93 (Fig. 31) engaging slots 95 on the guides.

It will be understood that when the last is placed with its bottom upon the heel and ball supports and between the toe and side positioning stops heretofore described, the upper, which is then extended loosely over the last, is smoothed out by the operative and is placed upon the lower jaws of the open side and toe grippers. The upper having been placed in this position, in the embodiment of the invention here illustrated, these grippers are preferably all closed simultaneously by the operative by actuating the two pairs of push rods 88 and 104, through the mechanism shown more particularly in Figs. 2, 9 and 10. As there shown, a treadle lever 106 (Fig. 1) is pivoted between its ends at 108 in the lower portion of the base 2. To the end opposite the treadle there is connected, by a yoke 106^x, the base of a yoke 110 which sustains a frame 112 forming a table extending at each side (Fig. 9) under the side gripper push rods 88 and rearwardly (Fig. 10) under the toe push rods 104. This table is vertically movable in guides 111 on the base of the machine. The toe gripper push rods 104 are joined together at a point above the table 112, as will be hereinafter explained, and their combined lower portion 104^x (Fig. 10) bears upon the table 112. With this arrangement, the toe push rods partake of any upward movement of the table, but at

the same time have free transverse movement relative thereto. The rod 104^x is guided in its vertical movement by a sleeve 114 carried by a bracket 116 sustained by 5 the curved guide 12 and its table 8. The table 112 is provided beneath each of the lower portions 88^x of the side gripper push rods, with auxiliary tables or supports 118 (Fig. 9) yieldingly supported, by means of 10 springs 120 mounted on the table 112, to have vertical movement relative to the table 112. On each of these auxiliary tables 118 bears the lower portion 88^x of one of the side gripper push rods, these parts being 15 guided in their vertical movement by sleeves 119 carried by brackets 228 sustained by the side gripper supporting blocks 56 (Fig. 8). When the table 112 is in its lower position, the springs 120 are not under tension 20 and they are preferably of a compressive strength substantially equal to the amount of pressure it is desired to place upon the upper at the sides of the shoe to hold the upper securely. This pressure is consider- 25 ably less than the pressure which must be used to force the jaws of the toe grippers close enough together to corrugate the upper at the toe of the shoe. From the construction thus described, which may of 30 course be varied by one skilled in the art, it will be seen that pressure on the treadle lever 106 by the operative will elevate the table 112 and thus actuate the four push rods 88 and 104 through pressure on their 35 lower portions 88^x and 104^x, to close the side and toe grippers, as hereinbefore explained. When sufficient pressure has been put upon the upper at the sides of the last by the 40 grippers to enable them to grip the upper firmly, the springs 120 begin to compress and continued pressure on the treadle 106 will continue to move the toe push rods 104 to corrugate the margin of the upper at the 45 toe of the shoe without further pressure upon the upper at its sides.

After the grippers are closed upon the stock, in pulling it over it should be both stretched and correctly positioned on the last and finally its margin placed adacent the 50 insole in position to be secured thereto. Much better results are obtained by stretching the upper before it is placed entirely about and in contact with the curved portion of the fore part of the last than if the 55 stretching were done after this operation, as by the former method frictional contact with the last is eliminated and more uniform results secured. This may be accomplished by any suitable form of mechanism 60 wherein the stretching is performed in advance of or before the completion of the overplacing operation. In the illustrated embodiment of the invention I preferably provide means for stretching the upper 65 while it is still held in the position assumed

when the upper and last are assembled, and such position I will hereinafter refer to for identification as in substantially a single plane, and tightly gripped by the side and toe grippers. One of the preferred forms of mechanism for performing this position- 70 ing and stretching operation is shown in Figs. 1, 2, 4, 7 and 9. First describing the means for drawing the upper longitudinally of the last, it should be noted that when the 75 last is placed on its supports the toe position- 80 ing stop 52 is so close to the toe grippers that the center of curvature of the guides 92 is well within the edge of the last. Obviously as the grippers are moved down their curved guides, in order to place the 85 upper tightly and snugly about the last at its edge the most convenient location for the center of curvature of the guide is in a position near or at the edge of the last. The longitudinal drawing of the upper is prefer- 90 ably performed by moving the last forwardly of the machine or heel-ward while the upper is held by the toe grippers which remain stationary. With the machine of 95 the embodiment of the invention illustrated, in practice, when this stretching and position- 100 ing of the upper is completed, the edge of the last will have preferably been brought to substantially the vertical plane of the center of curvature of the guides 92. This movement of the last will also bring the edge of the last at the tip of the toe to a position substantially above the center of curvature of the circular guide 12 which 105 sustains the toe gripper supports. Refer- 110 ring to Figs. 2 and 4 the toe stop 52 is shown as mounted upon one end of a link 122, which, in turn, is pivoted to one end of an arm 124, pivotally mounted by its other end upon the toe block 18. The toe block 18 is also provided with a transversely extending pivot pin 126, on which a lever 128 is ful- 115 crumed centrally. One end of this lever is adapted to engage the arm 124 near its upper end but is normally kept out of engagement therewith by means of a spring 132, pressing against its other end 133. This spring is mounted upon a pin 134, piv- 120 otted to lever 128, and has bearings against a collar 135 on said pin and an abutment 136 on the toe block 18, the pin 134 being free to pass through the abutment 136. By forcing the end 133 of lever 128 against the pressure of the spring 132 the end 130 of said lever 115 is brought into engagement with the arm 124, the movement of which about its pivot on the block 18 will force the toe stop 52 forward, carrying the last heelward within the upper and with it the heel support, the heel support being guided in its movement by the pins 30, said movement elongating the springs 84. As the upper is held from movement by the toe grippers, which remain 125 stationary, such a movement of the last will 130

stretch the upper longitudinally as is desired. This movement is preferably under control of the operative through a hand lever 138 (see Fig. 8) which, as here shown, 5 is at the left hand side of the machine and is mounted on a transversely extending rock shaft 140, carrying a cam surface 142, which, on movement of the rock shaft, is adapted to engage the end 133 of the lever 10 128 to force it against the tension of the spring 132 and thus bring the upper end of lever 128 forwardly and with it the last through the toe stop 52.

As noted the upper should also be positioned and stretched transversely of the last as well as longitudinally. In the embodiment of the invention herein illustrated the preferred means for performing this operation is under control of the operative and is 20 best shown in Figs. 1, 7, 9 and 38. Loosely mounted by one end on the pivot pin 66 of each of the side grippers are plungers 144 (Fig. 34), their other ends entering barrels or sockets 146 mounted on the carriage 60, 25 which barrels contain light springs 148 that act normally to maintain the pivot pins 66 against set screws 67 (Fig. 32) in the inner ends of the slot 64 in the carriage 60 during the closing of the gripper jaws. The tension of these springs may be regulated by 30 means of screw tops 147, in the outer ends of the barrels 146. If further pressure is now placed on the arms 86 of jaw closing levers 76 after the jaws have been closed 35 both the pairs of side grippers will be drawn outwardly bodily in their respective slots 64, stretching the upper and compressing the springs 148 the pawl and ratchet lock 82, 84, holding the grippers in whatever outward position they are placed. I prefer to place this further pressure on the arms 86 through additional movement of the push rods 88 although other convenient means might be employed. The mechanism which 40 I prefer to use, to provide for the additional movement of the side gripper push rods is best shown in Figs. 1, 8 and 10. Referring to said figures a hand lever 150 (Fig. 1) is pivotally mounted on a stud 149 at one side 45 of the frame, preferably the side opposite the lever 138 controlling the longitudinal stretching of the upper. The lever 150 is in the form of a bell crank, the arms being of such proportions that considerable movement of the handle arm imparts but slight movement to the other arm 151. The arm 151 is connected by a link 152 to one end of a lever 153 secured between its ends to a rock shaft 154 extending transversely of the machine at about the height of the auxiliary tables 118 supporting the side gripper push rods. The other end of the lever 153 is loosely connected to a pin 155 projecting from one of the tables 118, through slots 55 157 (Fig. 9) in the table 112 and machine

frame, suitably formed to take care of the vertical movement of the pin. The other auxiliary table is similarly connected to the rock shaft 154 through an arm 153* engaging a pin 155* on the table. Pressure 70 on lever 150, as here shown toward the rear of the machine, will actuate the rock shaft 154 to raise the auxiliary tables 118 and with them the push rods 88 which, as before explained, will move the side grippers outwardly and stretch the upper transversely. During this movement the upper will first be brought "down to the wood", that is, be brought into contact with the last at the instep, and then stretched, and the slot 64 80 should be long enough to allow the greatest outward movement required.

With the construction described the controlling levers 138 and 150 are so arranged that the operative may actuate both simultaneously, so that he may position and stretch the upper longitudinally and transversely at the same time. As he is pushing on one lever and pulling on the other he can readily "feel" the pull on the upper in 90 either direction in which the upper is being stretched. The last being positioned on the machine bottom down, with the upper in full view of the operative at all times, the stretching of the upper can be performed 95 with great nicety and the best results obtained. To aid the operative in drawing the upper longitudinally to such an extent that the tip line will always be brought to correct position with relation to the toe of 100 the finished shoe, no matter what size of last is in the machine, an adjustable tip line gage 156 (see Fig. 3) is mounted upon the frame of the machine. The construction and action of this gage will be explained herein- 105 after.

After the upper has been stretched to the satisfaction of the operative, and correctly positioned relatively to the tip gage 156, to complete the pulling over operation, it 110 should be placed in such position about the last that its margin is within the last edge and adjacent the insole in position to be secured thereto. In the illustrated embodiment of the invention this is preferably 115 done after the completion of the stretching operation by the mechanism, one form of which is best illustrated in Figs. 1, 10, and 17 to 28. Mounted in the lower part of the frame is a power shaft 158 (Figs. 1 and 10), 120 which may be thrown into operation by means of any suitable form of start and stop motion for rotating the shaft preferably through one revolution, including a convenient form of clutch (not shown). The shaft 125 158 carries a cam disk 160 having a cam groove 162 in which rides a roll 164, mounted upon an arm 166, preferably provided with guides 168, embracing the shaft 158, for guiding the arm in a right line. The 130

arm 166 has pivoted thereon a block 170, which block is in turn secured to a vertically movable rod 172. The rod 172 is guided by a sleeve 174 carried by a hanger 175 (Figs. 5 10 and 28) depending from and movable with the frame 14 for a purpose hereinafter explained. The rod 172 is also provided with a head, to be described in detail hereinafter, to which are pivoted two actuating 10 rods 176 for drawing the carriages 60, on which the side grippers are mounted, downwardly in their curved guides 59, and also with two rods 178 for similarly drawing the carriages 94 on which the toe grippers 15 are mounted, downwardly in their curved guides 92. Each of the actuating rods 176 and 178 is provided at its upper end with a slot 180, each of the slots engaging pins 184 one on each of the four gripper carriages, 20 these pins projecting through slots 185 in the curved gripper carriage guides a suitable distance so that such engagement may be effected. The cam disk 160 is so designed that as it rotates, the actuating rods will be 25 drawn downwardly simultaneously and with them all four of the carriages carrying the side and toe grippers. This downward movement of the grippers in their curved guides operates to place the stretched upper 30 about the curvature of the toe portion of the last and this action will be continued by means of the cam grooves 162 until the upper is brought to a position where it extends at substantially right angles to the plane of 35 the insole (see Fig. 22). Preferably, though not necessarily, other means than the cam 162 are thereafter employed to place the margin of the upper held by the grippers adjacent the insole in proper position to be secured thereto. The entire movement 40 of the grippers is, however, carried forward continuously and preferably automatically.

At a proper time during the forward 45 movement of the grippers the position of the toe and side positioning stops relative to the last should be changed, as for instance by removing them from their engagement with the last, so that they will not interfere 50 with the operation of placing the upper about the last and adjacent the insole. By the embodiment of the invention herein shown, the toe stop 52 and the side stops 54, are preferably withdrawn from the last, as 55 is best illustrated in Figs. 4, 24 and 26.

The side positioning stops 54 are constructed alike and are retracted by similar mechanisms, so that a description of one will suffice for both. Each stop is mounted 60 upon a slide 200 (Figs. 24 and 28), which is normally held upwardly with the stop against the last by means of a spring 202, secured at one end to a pin on the slide 200 and at its other end to a pin on a bracket 204 (Figs. 26 and 28), secured to the side grip-

per support 58. As here shown, the securing means for the bracket 204 consists of screws 205, the slide 200 being slotted and guided in its movements by said screws. The slide 200 is provided with a tailpiece 70 206, which projects across the slot 185 down which the pin 184 on the side gripper carriage travels, so that at the proper time the tailpiece is engaged by said pin and moved downwardly with it. The stop 54 is thus 75 retracted to a position where it will not interfere with the operation of placing the upper at the side of the last adjacent the insole.

To the link 122, carrying the toe stop 52, 80 through a pin and slot connection, is mounted a rod 186 (Fig. 4), which extends downwardly, and is suitably guided to have vertical movement in the toe block 18. This rod 186 is provided with a tailpiece 188 85 (Figs. 24 and 28) which projects into the path of movement of any convenient downwardly movable part of the machine, preferably one of the supports 200 for the side positioning stops 54. When the grippers 90 with the upper securely held between them have brought the upper to the proper position the tailpiece will be engaged by an ear 201 on one of the supports 200, as it moves downwardly in retracting the side stops and 95 this will draw the link 122 downwardly. The link 122 is preferably kept normally elevated by means of a spring plunger 190 (Fig. 4), which may be mounted in a socket in the toe block 18. 100

The toe stop 52 having been withdrawn from its engagement with the toe of the last, it should also be withdrawn within the edge of the last so that it will not interfere with the operation of placing the upper at the toe of the shoe adjacent the insole. To gain this end, a spring 192 (Fig. 4) is mounted upon a pin 194, which is swiveled at one end in the end 130 of the lever 128, its other end passing loosely through a second block 196 swiveled in the link 124. This spring 192 is normally of such length that when not under compression it aids in maintaining the end 130 of the lever 128 out of engagement with the arm 124. This spring 192 will be compressed when the cam 142 is turned to throw the end 130 of the lever 128 into engagement with the arm 124 to move it and the toe stop 52 forwardly, but as soon as the toe stop is retracted from its engagement with the last the spring 192 will be allowed to expand and swing the arm 124 farther about its pivot on the toe block 18 and thus bring the stop 52 forward within the edge of the last and under the insole, as 125 shown by dotted lines Fig. 4. The pin on which the block 196 is swiveled also passes through a slot in one end of a link 198 (Fig. 2), the other end of said link being pivoted to the end 130 of lever 128. This pin and 130

slot connection limits the forward movement of the toe stop 52 after it has been disengaged from the last. This connection also performs the further function of drawing the link 122 with its toe stop 52 rearwardly again after the cam 142 has been retracted from engagement with the lower end 133 of the lever 128, thus allowing the spring 132 to exert pressure against said lower end to force the lever about its pivot, and move its upper end 130 again rearward.

During the retraction of the side and toe positioning stops the continued rotation of the cam 162 operates to continue the movement of the side and toe grippers down their curved guideways and this cam is so designed that at the time the upper is brought by the grippers to a position at substantially right angles to the plane of the bottom of the last there is a dwell in the cam. The preferred means to be used in the illustrated form of the invention for continuing the movement of the grimmers from this position in a direction to place the stretched upper adjacent the insole in proper position so that it may be secured thereto is best shown in Figs. 1, 9, 10 and

14 to 28. On shaft 158 is a second cam disk 208, provided with a cam groove 210 in which is adapted to ride a roll 212, mounted on one arm of a bell crank lever 214 (Fig. 10), pivoted at 216 on the base of the frame. The end of the bell crank lever 214 carrying the roll 212 is suitably connected through a link 213 (Fig. 10) to a sleeve 218, mounted upon a guide rod 220. This link 213 is pivoted on a lug 215 which in turn is pivoted on the lever 214 whereby the link may have movement in two directions. The other end of the link has a universal connection, as a ball and socket joint 217, with the sleeve 218. The guide rod 220 depends from the block 56 sustaining one of the side gripper supports 58 and preferably lies directly beneath the last edge. A similar connection to that just described is provided between the bell crank lever 214 and a similar rod 220 on the other side of the machine, and a description of further connection between these parts and the side gripper supports and operation thereof for one of the side gripper supports will suffice for both. The sleeve 218 preferably carries a pair of anti-friction rollers 222 (Fig. 9) between which passes a cam shaped end 223 of a lever 224 pivoted at 226 upon a bracket 228 (Figs. 9 and 11) secured to the guide rod 220. The other end of lever 224 is pivoted to one end of a link 230, the other end of which is pivoted upon a pin 232 on the side gripper support 58.

Just at the time that the upper has been brought to a position at substantially right angles to the bottom of the last the cam groove 210 operates to move the roll 212

and with it the bell crank lever 214, which motion moves the sleeve 218 down its guide 220 and as the antifriction rollers 222 pass down the cam shaped end 223 of the lever 224 said lever is swung about its pivot 226 on the bracket 228 in a direction to move the gripper support 58 inwardly on its guide 57 so that the margin of the upper held by the grippers is placed within the last edge and under the insole. Preferably, as this movement is taking place the grippers are also moved upwardly to place the stretched upper adjacent the insole in position to be secured thereto. This upward movement is effected by means of the inward movement, for the overlapping portion of the upper is held tightly stretched between the last and the grippers and therefore as this portion is moved inwardly it will also tend to move upwardly about the edge of the insole as a center. To enable such movement to take place is the function of short link 78 which up to this time has remained in alignment with the direction of pressure upon it. The link 78 is utilized to this end in the following manner.

Pivoted upon a lug 234 upon the block 58 is an inwardly extending arm 236 (Figs. 24 to 28). The arm 236 is provided with a slot or recess 242 which is preferably formed between a hooked end 238 on the arm and a block 240 also on the arm. This block is preferably provided with a beveled surface and is spaced sufficiently far from the hook 238 to form a recess of substantially the same width as the end of the link 72 connecting the grippers with their actuating lever 76. The arm 236 is yieldingly supported by means of a light spring 244 in such position that the block 240 is normally maintained in the path of movement of the outer end of the link 72 when said link is in its outward position after the grippers have been closed. In the descent of the gripper carriage 60 down its curved guide 59 the outer end of the link 72, carrying the short link 78, rides upon the beveled surface of the block 240 thus depresses the arm 236 and drops into the recess 242, this being timed to occur just as the cam roll 164 reaches the dwell herefore mentioned in the cam groove 162. As the side gripper support moves inward the outer end of the short link 78 is held from inward movement by being in the recess 242, as the arm 236 does not move with support 58, and, as the inner end of the link 78 is connected to the actuating lever 76 which also moves inward with the support, movement of this lever 76 will carry the inner end of the short link 78 inward with it and said link will therefore be moved to a position where it can act in effect as a crank, its outer end moving up-

wardly in the recess 242, in consequence of the straining action of the upper, and allowing the link 72 and the side grippers carried by said link, to follow the upward draw of the upper, said grippers having motion in the slots 64 in the lugs 62 formed on the gripper carriage 60. It is thus seen that a movement of the bell crank lever 214 will not only force the side grippers inwardly but, through the action of the upper and of the stationary arm 236 and its recess 242, will also allow them to move upwardly so that the margin of the upper is carried finally to a position within the last edge and adjacent the insole and held there.

Preferably, though not necessarily, movement of the bell crank lever 214 also actuates the toe gripper supports to place the upper under and adjacent the insole at the toe. Referring to Figs. 14 to 23, the arm 246 of bell crank lever 214 is suitably connected, as will be described, to the sliding table 8, which carries the curved guide 12 on which the supports carrying the toe grippers are mounted. Movement of the bell crank lever 214 in one direction will operate to move the table 8 forwardly between its gibs 10 and with it the toe gripper supporting guide 12 thus carrying the edge of the upper held between both pairs of grippers inwardly under the last. This movement places the center of curvature of the guide 12 within the edge of the last. At the rear of the curved guide 12 is a second curved guide 248 (Fig. 15) which, however, is mounted upon the gibs 10 so that it will not partake of the forward movement imparted to the grippers by the bell crank lever 214. The curvature of this guide 248 is such that after the guide 12 has been moved forward, the centers of curvature of these guides will coincide so that the guideways will be concentric. In practice, this forward movement will preferably be substantially uniform for all styles and sizes and will also be equal to the amount of throw imparted by the cam shaped ends 223 of levers 224. Mounted to slide in the curved guide 248 are two blocks 250 (Figs. 17 to 23) each of which sustains a yieldingly supported arm 251 projecting forwardly within the side plates of the gripper supports and beneath the path of their carriages 94. (See Fig. 21). These arms are preferably similar in all respects to the arms 236 heretofore described for the side grippers. As the toe gripper carriages move downward the ends of the links 72 for closing the grippers engage in the recesses formed on the yieldingly mounted arms 251, as heretofore described for the side grippers. Therefore, during the inward movement of the toe gripper supports the grippers are also allowed to be drawn

upwardly in the slots 96 in a similar manner to that described for the side grippers, so that the margin of the upper at the toe of the last is at the completion of this stage of the pulling over operation, placed adjacent the insole as well as within the edge of the last. It will be noted, however, that the inner edges of the toe grippers are not at this time parallel to the edges of the last and before the upper is secured in position it is desirable that the toe gripper supports be moved to bring their grippers in this relation to the last edge. In this embodiment of the invention, the preferred mechanism for moving the toe gripper in parallelism with the edge of the last is shown most clearly in Figs. 5, 6, 10 and 16. Through the mechanism there shown the toe grippers are given a turning movement by moving their supports in the curved guide 12, so that their edges may be brought in parallelism with the edges of the last. Each of the toe gripper supports is provided with a pin 252 (Figs. 6 and 19) at its base which pins extend downwardly through slots 254 (Fig. 16) in the bottom of the curved guide 12. To these pins are pivoted the knuckle of toggle links 256, the outer ends of which are both pivoted upon the pin 258, carried by a socketed block 260 resting upon a table 7 (Fig. 10) forming part of the head. Through the block 260 loosely extends a rod or pin 262, which rod is pivotally mounted at its inner end on a pin 264 upon the sliding table 8. The rod 262 carries a spring 266, which normally bears upon the block 260 to keep the toggle 256 closed and the pins 252 on the toe gripper supports at the inner ends of their slots 254 in the guide 12. The socketed block 260 is connected to the outer end 246 of the bell crank lever 214, through a universal connection 268 (Fig. 10) including a spring 270, whereby the connection is made yielding, this spring being stronger than the spring 266. The first portion of the movement of the bell crank lever imparted from the cam groove 210 in the cam disks 208 will carry with it the table 8, the socketed block 260 with its spring 266, and the connection 268 with its spring 270, without compressing either of the springs or spreading the toggle 256. The table 8, however, after a short movement, is brought to rest by abutting against a stationary part of the frame, as here shown, the rear bracket 6, and further movement of the bell crank lever 214, will first continue the movement of the socketed block 260 to compress the weaker springs 266 which moves the pin 258 forward, thus spreading the toggle 256 and forcing the pins 252 on the toe gripper supports outwardly in their slots 254 until said supports engage stops 272 (Figs. 5 and 6) adjustable in short guides 273 (Fig. 16) in 180

the ends of curved guide 12. The reason for forming the curved guide 248 concentric with the curved guide 12 when the latter guide has been forced inwardly will now be clear, for the blocks 250 carrying the yielding arms 251, although they do not partake of the inward movement of the curved guide 12, must be carried with the toe gripper supports as they are moved outwardly in said guide after the inward movement has taken place. If the style of the shoe being operated upon has a pointed toe this outward movement of the toe grippers in the guide 12 is considerable, that is, the stops 272 are adjusted so as to be near the ends of said guide, but if a round toed shoe is being operated upon the stops 272 are placed nearer together, for the movement of the toe grippers to bring their inner edges in parallelism with the edge of the last is necessarily not so great. The cam 210, however, must be designed so as to be able to give the greatest movement required and, therefore, when operating upon a round toed shoe there will be still further movement of the bell crank lever 214 after the toe gripper supports have engaged the stops 272.

The spring 270, mounted between the socketed block 260 and the bell crank lever, is designed to yield at this time and thus take up this extra movement. The operation of bringing the upper under the bottom of the last and placing it adjacent the insole is preferably performed by movement of all four of the grippers simultaneously through the action of the cam 210, the movement for bringing the toe grippers parallel to the edge of the last preferably occurring afterward through continued movement of the same cam. The action however, is such that the upper is placed in proper position to be secured to the last at all four points at substantially the same instant of time. It is not necessary to move the side grippers in parallelism with the edge of the last as they are already in this position (see Figs. 2 and 5) and are kept so normally no matter what size or style of shoe is being operated upon, as will be hereinafter described.

The stretched upper having been brought into position to be secured, it is desirable to provide means for inserting fasteners of some kind through the upper and into the insole to hold the former in position when the shoe is removed from the machine. The preferred mechanism for performing this operation, in the embodiment of the invention herein illustrated, is best shown in Figs. 17 to 34. The actuating mechanism for the fastener drivers is substantially the same for both the sides and the toe of the last, therefore a description of one will suffice for all. Referring more particularly to Fig. 19, to each of the gripper supports is pivoted a

hammer lever 274, the upper surface of which is curved concentrically with the vertical guides of the gripper support. This hammer lever bears upon a conical block 276 provided with a pin 277 fitting within one end of a coiled spring 278, the other end of which bears upon the collar of a sleeve 280 having a socketed bearing upon a screw 282 threaded into a lug 284 upon the gripper support. The tension of the spring 278 may thus be regulated by the screw 282. The spring 278 normally keeps the hammer 274 elevated turning the same about its pivot. The hammer is maintained in its retracted position, with spring 278 under compression, by means of a spring pressed latch 286 carried by the gripper support and adapted to move into bearing engagement with the hammer surface 275. The spring 278 is appropriately compressed by suitable mechanism, such, for instance, as shown. Referring to Figs. 24 to 28, in the case of the side grippers, the hammer 274 is provided with a pin 288, which is suitably connected, as by links, to one end of a lever 290 pivoted upon the gripper support 58. The actuating rod 176 carries a pivotally mounted spring pressed pawl 292 having an engaging face normally projecting beyond the face of the rod adjacent the lever 290. This pawl is provided with means, as a stop 293, arranged to engage the rod 176, to prevent its engaging face projecting too far beyond the face of the rod. The lever 290 is provided on its side adjacent the actuating rod with a lug 294. This lug is so located on the end of the lever 290 on the opposite side of its pivot from the pin 288, that as the rod 176 ascends upon its back stroke the projecting end of the pawl 292 will engage the lug 294 and thus move the lever 290 about its pivot in a direction to retract the hammer 274 and compress the hammer spring 278. As the rod 176 moves upwardly, owing to the curvature of the guides 59, it is also moved outwardly. The lug 294 is so formed that the pawl 292 disengages itself therefrom, by reason of its outward movement, just as the surface 275 of the hammer has been brought to a position where the latch 286 engages it through pressure from its spring 296. The upper surface of the lug 294 is preferably beveled so that the pawl 292 may pass it freely on the downward movement of the actuating rod. Referring to Figs. 17 to 21, in the case of the toe grippers, the hammer 274 is retracted by devices on the actuating rod 178 and the lever 290 in a similar manner to that just described for the side grippers. In this instance, however, it is desirable to maintain the actuating rods close to the guides 92 and therefore I place a boss 294* on one side of the actuating rod 178 adapted to engage a spring pressed pawl 292* on the lever 290. On the down stroke this pawl gives and

allows the boss 294^x to pass it, but on the up stroke of the actuating rod the pawl is held from movement when it is engaged by the boss 294^x by engaging the lever 290 and the lever is therefore moved in a direction to compress the hammer spring 278. The outward movement of the actuating rod withdraws the boss from beneath the pawl at the time the latch 286 engages the hammer surface 275.

In the preferred form of fastener inserting mechanism, in addition to carrying the grippers, the carriage 60 has mounted upon it a driver bar 300, preferably carried with 15 in a sleeve 302, pivoted upon the carriage. This driver bar is provided at its outer end with a head or button 304, Figs. 17 and 19, and carries between said button and the sleeve 302 a spring 306 of some strength, but 20 weaker than the spring 278, for normally keeping the driver bar retracted and the driver head 308 in engagement with the inner end of the sleeve 302. With the last resting upon the machine bottom down, the 25 fasteners must be driven into the shoe upwardly, and, therefore, it is more convenient to use means other than gravity for obtaining a fastener from a source of supply and placing it in position to be driven by the actuation of the driver 300 through the hammer 274. Frequently, also, on account of the location of or form of discharge from the source of fastener supply, the fasteners need to be either partially or wholly inverted while being conveyed to driving position. To gain these ends I prefer to provide the driver with means for engaging a fastener, so that it may be carried by the driver from the source of supply to driving position. The driver 300 thus forms in effect 40 means for conveying a fastener into proper position for insertion and for holding the fastener in such position until inserted. Referring to Figs. 41 and 42, showing one construction, between ears 310 on the driver head is pivoted a small two-armed lever 312, having one of its arms bearing upon a spring 314 resting in a socket on the top of the driver head 308, its other end forming a spring 45 pressed catch bearing upon the end of the driver head. This catch is adapted to engage the under surface of the head of a fastener holding said head firmly against the head of the driver with the fastener extending in 50 alignment with the driver. In the securing operation I prefer to use multipointed fasteners, such, for instance, as staples, for the reason that such fasteners provide in one piece a plurality of holding points necessary to 55 secure the upper properly at the sides of the shoe in the pulling over operation and, for the further reason that in this embodiment of the invention, where I prefer to flute or corrugate the upper at the toe of the last to 60 shape it thereto, such shaped upper is held 65

in place better by being secured at four or more points than if secured at only two points. Furthermore, staples are more readily handled and more quickly and easily removed from the work if such removal is 70 found necessary than if two single tacks were used, as is now customary. It should be understood, however, that I do not limit myself to the use of staples, as the form of driver which I have described may readily be adapted to carry various kinds of fasteners. In using staples I prefer to provide the driver head 308 with a transverse shoulder or abutment 315, (Fig. 41), against which the head of the staple rests when held by 75 the catch 312 in position against the head of the driver, said shoulder aiding in maintaining the staple in alignment with the driver. Each gripper support is provided with an abutment, as a pin 316, against which the sleeve 302 on the outer side of its pivotal point bears when the gripper carriage 60 is in the upper end of its curved guide, and said carriage is connected to the sleeve 302 by a spring 318 located in such position as 80 to normally maintain the driver 300 in engagement with the upper side of the gripper jaw 61, (see Fig. 19). The pin 316 is so positioned that when the gripper carriage 60 reaches the upper end of its stroke the driver will have been forced away from the jaw 61 and brought to a proper position to receive a fastener from the source of supply, (see Fig. 44). This is the position it occupies during the time that the grippers 85 are being closed upon the upper preparatory to moving downward in their curved guides. The gripper support 58 also carries a spring 90 pressed plunger 320, against which the spring pressed arm of the catch lever 312 95 engages when the carriage 60 is at the top of its stroke, thus keeping the catch open for the reception of a fastener.

I will now describe the means for supplying fasteners, which in the present instance 100 are staples, to the drivers. I prefer to use the mechanism shown in Figs. 35 to 47, and as this mechanism is the same for all four drivers a description with relation to one of them will suffice for all. The toe gripper 105 support 92 has secured thereon a vertically arranged casing 322. This casing is designed to sustain the supply of staples for the driver and also the means for selecting them one at a time therefrom and presenting 110 such selected staple to the catch upon the driver head. Within the casing 322 and supported thereby is a longitudinally movable sleeve 324, held in any particular position to which it is moved by any suitable 115 means, as friction pads 326, (Fig. 40) sustained by the casing and held in position by screws 328. The sleeve 324 is provided with a lower box like end 330, forming a horizontally arranged guideway for a block 332 120

125 130

(Figs. 40 and 43) which closes the lower end of the sleeve. This block is constructed and arranged to receive fasteners from the source of supply and present them to the driver in position to be engaged by the catch 312 and for convenience will be termed a "presenter."

Any convenient means may be used for supplying staples to the presenter block 332 but in this form of the invention I prefer to use an open ended container 334 (Fig. 40) in which a number of staples have been placed, one upon the other, so that the entire column so formed will rest upon the 10 presenter block by force of gravity. The presenter block is so constructed that on each forward movement within its guideway it will carry the lowermost staple of the column into position to be engaged and held by 15 the catch on the driver head and thereafter carried into driving position, the block then returning again beneath the column of staples which have settled down so that they again rest upon its surface. Preferably 20 these containers 334 are portable members, and therefore means should be provided for securing the staples therein while they are carried to the machine and placed within the sleeve 324. To this end each container is 25 preferably provided with a central longitudinal abutment 336 extending from one side but leaving sufficient space between it and the other sides for the reception of the staples. The container thus forms, in effect, 30 a chute for the staples. The abutment 336 is provided with a central aperture 338, through which extends a locking rod 340, provided at its lower end with a pair of curved spring fingers 342 which bear against 35 the sides of the container and extend beneath the column of staples preventing them from passing out of the open bottom. The locking rod 340 is provided with a thumb piece 344 so that after the container is 40 placed within the sleeve 324 the rod may be drawn upwardly, through which movement the spring fingers 342 are drawn inwardly from beneath the staples by their curved surfaces riding past friction rollers or pins 45 346 carried in the lower end of the abutment 336 the staples being thus allowed to drop until they rest upon the upper surface of the presenter block 332 in position to be selected one by one for insertion. The locking rod 50 340 is maintained in its retracted position by a pin and slot connection 348 between it and the abutment 336.

The presenter block 332 is shown most clearly in Fig. 43 and is provided with a 55 recessed surface forming a cut away portion 350 extending along either side of the top and across the front end, within which the lowermost staple of the column in the container 334 rests (see Fig. 38) so that the 60 block may be moved forwardly in its guide

330 carrying the lowermost staple until its head projects beyond the wall of the casing 322. The presenter block 332 is also provided with grooves 352 (Fig. 43) in its front end, or face, extending backwardly for 70 almost the length of the shanks or legs of the staples, and with a central, vertically arranged groove 354, just back of the head of a staple resting in the cut away portion 350. The sleeve 324 is provided with a pin 356 75 (Fig. 40), extending through a slot 358 in the casing 322 and on this pin is pivoted a lever 360 (Fig. 35), having a short arm 362, provided with a pin 364, which projects between ears 366 on the casing 322, and a 80 longer arm 368 having a slotted end 370, embracing a pin 372 upon the presenter block 332 extending through a slot 374 in one side of the guide 330. It will thus be seen that if the sleeve 324 be given a movement 85 in one direction the arm 368 of the lever 360 will be given a motion about the pivot pin 364, which has no vertical movement, whereby the presenter block 332 will be given a 90 movement in one direction, and, conversely, a movement of the sleeve 324 in the other direction will through the same connections, move the presenter block in the opposite direction. As here shown, the connections are so arranged that a downward movement of 95 the sleeve 324 will retract the presenter block within its guideway 330, while when the sleeve is in its upward position with its lower end against the lower end of the casing 322 the presenter block is forced outwardly so that it projects beyond the end of 100 its guideway and with its end beneath the head of the driver 300 in such position that the head of the staple carried by the presenter block is beneath the shoulder 315 between the catch 312 and the driver head 308. When the gripper carriage and driver are 105 at the top of their stroke the sleeve 324 is up and the presenter block 332 is in its outward position through connections now to 110 be explained.

The means which I prefer to use for imparting movement to the sleeve 324 is best shown in Figs. 44 to 47. A forked arm 376 is mounted to have movement with the 115 gripper carriage 94, preferably upon the carriage itself, the upper arm 375 of this fork being somewhat shorter than the lower arm 377. When the gripper carriage 94 is at the upper end of its stroke the lower arm 377 is 120 in engagement with a pin 378, of less diameter than the space between the arms 375 and 377, said pin projecting from a convenient part of the sleeve 324. As the gripper carriage starts to move down in its curved 125 guideway it carries the driver 300 with it and no downward movement is imparted to the sleeve 324 until the arm 375 engages the pin 378. During this lost motion the driver has been brought down sufficiently to bring 130

the head of the staple resting upon the now forwardly extending presenter block against the shoulder 315 on the driver head, the catch 312 passing into the vertical slot 354 in the presenter block. The catch 312 on the driver is maintained open so that the staple may enter behind it by means of the spring pressed plunger 320 which through its spring follows the driver in its descent 5 until stop nuts 321 engage the gripper support and prevent further downward movement of the plunger, at which time, however, the staple has been placed against the shoulder 315 and is in proper position to be 10 engaged by the catch 312 to hold it upon the driver head (see Fig. 45). At this time the head of the driver is being forced downwardly by the action of spring 318 upon the sleeve 302, this movement tending to bring 15 the driver head against the upper surface of the gripper jaw 61. At this time, also, the arm 375 begins to bear upon the pin 378 and carries the sleeve 324 downwardly with it, which motion of the sleeve acts to retract 20 the presenter block 332 in its guideway 330, as heretofore explained (see Fig. 46). Owing to the curved line in which the gripper carriage 94 descends, the forked arm 376 tends 25 to slide off the pin 378, the arm, however, being made long enough to engage the pin 30 for a sufficient length of time to move the presenter block 332 far enough back to again 30 rest in proper position beneath the column of staples for receiving upon its cut away 35 portion 350 the staple now at the bottom of the column. As the presenter block is retracted the driver bar 300, carrying a staple, continues to move down with the carriage 40 94, the legs of the staple passing down through the side slots 352 in the presenter block, as the latter is being retracted. The spring 318 having brought the driver head 45 against the upper side of the gripper jaw 61, the driver and grippers both travel together in this relation down the curved 50 guide in the gripper support, and in their descent the button 304 on the end of the driver engages the surface 275 of the hammer 274, the spring 306 yielding, if necessary, during this engagement. The parts 55 having reached the position shown in Fig. 23, under the action of the cam 162, all the gripper supports are then moved inwardly and the grippers are moved upwardly as 60 heretofore described through the action of the cam 210. During this latter movement the springs 306 on the drivers again elongate, so that the buttons 304 are kept in constant engagement with the surfaces 275 of 65 the hammers 274. As the side gripper supports reach the end of their inward movement the upper has been placed in proper position adjacent the insole for the insertion of the fasteners and at this time the 70 latches 286, which hold the hammers 275 in

retracted position, are tripped, the hammers are allowed to move forward under the action of the springs 278 to impart a driving blow to the drivers 300 and insert the staples through the upper and into the insole. The last is held in position against the force of this blow by reason of the upper still being firmly held by the grippers. 75

The means used for tripping the latches 286 for the side grippers may be different from that used for the toe grippers. As the side gripper supports move inward a tail 285 (Figs. 24 and 27) on each latch engages a pin 287 carried by the stationary block 56 and the latches are thus turned about their pivots 289 to remove them from their engagement with the hammer 274, allowing it to move forward. In the case of the toe grippers this release of the hammer should not occur until after the grippers have been moved outwardly in the curved guide 12 to bring them in parallelism with the edge of the last, which movement as heretofore described takes place after the completion of the inward movement of the gripper supports, although substantially simultaneously therewith. To this end the stops 272 in the ends of the circular guide 12 may be utilized to engage the tails or extensions 285 (Figs. 5 and 21) of the latches 286 for the toe 90 driver hammers to trip said latches and allow the hammers to impart their driving blow. The tripping of all four latches and the driving of all four fasteners thus occurs substantially simultaneously. 95

As the fasteners used in the pulling over operation are frequently withdrawn when the shoe is lasted, it is preferable to only partially insert them and to this end a lug 291, is mounted on each of the gripper supports adjacent the levers 290 so that upward movement of these levers is checked at such a time that the blow from the hammers 274 will effect only a partial drive. This result is also insured by reason of the construction 100 of the driver head. As the catch 312 lies between the head of the fastener and upper, the fastener is absolutely prevented from being driven beyond a point where this catch engages the upper. It is also desirable especially in pulling over "Good-year" shoes, to insert all fasteners at about the same distance from the edge of the last and preferably into the angle formed between the channel and channel lip. In this 105 embodiment of the invention the grippers are all moved inward beyond the edge of the last a definite distance and as the fasteners are inserted directly adjacent the grippers they must necessarily all be inserted the 110 same distance from the last edge. If in practice the grippers are moved inward say, one quarter of an inch, the fasteners would be inserted about three sixteenths of an inch 115 from the last edge which would ordinarily 120 125 130

place them in the angle above mentioned as is desired. In many styles of lasts the angle at the edge is very acute and the fasteners should therefore be inserted obliquely toward the center of the last. The angular position of the drivers with relation to the last bottom when in driving position provides for insertion of the fasteners in this manner. (See Figs. 23 and 28).

- 10 After the fasteners have been inserted through the upper and into the insole the carriages carrying the grippers, drivers and related mechanism, must be moved back to the upper ends of the curved guideways in 15 position to enable the drivers to seize another fastener for the succeeding operation, and this is preferably done automatically by continued movement of the same cams which bring the gripper carriages down 20 their guideways and move the grippers inward under the shoe. This operation is the same for all four of the grippers and a description for one will suffice for all. Referring more particularly to Fig. 28, as heretofore 25 described the actuating rod 176 is provided with a slot 180 at its upper end within which extends the pin 184 on the gripper carriage 60. When this carriage is at the bottom of its stroke said pin is in the upper 30 end of the slot 180 and before any upward movement will be imparted to the gripper carriage there will be loose play between the rod and pin until the lower end of the slot 180 engages said pin. During 35 this first portion of the upward movement a boss 181 on the slotted end of the actuating rod 176 will engage a tailpiece 380 secured to the pin 80 which carries the pawl 82. This tailpiece is so mounted that upward movement at this time will disengage 40 the pawl 82 from its ratchet 84, which will loosen the hold of the gripper jaws upon the upper. At this time also the lever 290 has been engaged by the pawl 292 on the 45 actuating rod and the hammer 274 is steadily drawn back. This movement allows the spring 306 to expand and, the nose of the catch being in engagement with the driven staple, causes the catch to open. 50 Further expansion of the spring withdraws the driver from its engagement with the driven staple and carries the driver away from the shoe through the sleeve 302. The grippers and drivers are thus all disengaged 55 from their engagement with the shoe simultaneously. Further movement of the rod 176 will continue to move the tailpiece 380 until an ear 83 upon the pawl 82 engages an ear 77 upon the lever 76 (see Figs. 32 60 and 33), thereby moving said lever about its pivotal point and forcing the link 72 inwardly along the slots in the legs of the gripper jaws, thus opening said jaws. This movement of the link 72 also withdraws its 65 end from the recess 242, in the spring,
- pressed arm 236. By this time the lower end of the slots 180 in the actuating rods have engaged the pins 184 on all the carriages and, as all the mechanisms carried by the carriages have now been freed from engagement with surrounding parts, a dwell is provided in the cam 162, and the cam 210 operates to actuate the bell crank lever 214 to close the toggle 256 and thus move the toe gripper supports first inwardly in the curved guide 12 and then outwardly in the longitudinal guide 10, and to move the side gripper supports outwardly on the ways 57 of the blocks 56. Continuing the description for a single pair of grippers, the cam 80 162 now comes into operation again and the gripper carriage 60 is moved upwardly in its curved guideway, the lower arms 377 of the forked arm 376 carried by the carriage in this movement engaging the pin 85 378 carried by the sleeve 324, moving said sleeve upwardly against the force of the friction blocks 326 and at the same time operating the lever 360 to bring the presenter block 332 with the lowermost staple of the 90 column in the container forward into position beneath the head of the driver 300 which has by this time passed the level of the block 332, so that on the next downward movement said staple may be in a position 95 to be engaged by the driver in a manner as heretofore explained.
- It will be understood that on the upward movement of the driver bar 300, owing to its position with the driver head against the upper side of the grippers, the pin 316 will be engaged before the grippers reach their upper position (see Fig. 47) and the driver sleeve will therefore be turned about its pivots elongating the spring 318 until at 100 the time the grippers reach their position of rest the driver lies in substantially the plane of the presenter block as is desired. At this time, also, the spring pressed arm of the catch 312 has engaged the plunger 320 compressing its spring and forcing it upwardly but also compressing the spring 314 of the catch and thus maintaining the catch in open position.
- It will be noted that as the gripper carriages move up and down in their curved guideways the push rods 88 and 104 for the side and toe gripper closing mechanisms should be either retracted a sufficient distance or otherwise moved so that they may 115 be cleared by the socketed ends 87 of the arms 86 of the levers 76. I prefer to move these rods outwardly and in the embodiment of the invention herein illustrated the preferred mechanism for performing this operation is best shown in Figs. 8 to 12. A description of the action of one of the side push rods will suffice for both. Referring to Figs. 8 and 9, the bracket 228 supported by the guide rod 220, carries guides 382, in 120 125 130

which a rod 384 is adapted to slide. This rod is provided with a pair of collars 386, secured thereto and between these collars and constructed so as to have a limited play therebetween is loosely mounted a sleeve 388, which sleeve is also secured to the lower portion 88^x of the push rod 88, which portion of the push rod is guided in its movement by the sleeve 119 as heretofore explained. With this construction the push rod is wholly sustained by the guide rod 220 and movement of said guide rod will carry the push rod with it. The sleeve 388 has pivoted thereto one end of a link 390, the other end of which link is pivoted at 391 to the push rod 88. It is thus seen that the push rod is in two portions which are connected through the sleeve 388 and link 390. The push rod 88 is provided with an angular extension 392, pivoted to the sliding rod 384 which extension is of such length that when the sleeve 388 is in engagement with its upper collar 386 the two portions of the push rod are in alinement and the upper portion lies directly beneath the socket 87 heretofore mentioned. A very similar mechanism is used to move the push rods 104 to a position where they will not be engaged by the sockets 87 as they move down and up with the toe gripper carriages. A single lower part 104^x (Fig. 10) is utilized for actuating both rods, having vertical movement in the bracket 116, and carrying a sleeve and collars as heretofore explained, for the side push rods. Above the sleeve and collars and secured to the guide rod is a two armed bracket 394 (Fig. 9) each arm of which has pivoted thereon a short stud 396, which studs are connected by a cross bar 397. Each of the studs 396 has swiveled thereon, and suitably secured; the lower end 398 of one of the toe push rods 104. The cross bar 397 is connected to the sleeve on the guide rod by a link 400 corresponding to the links 390 and the upper pivot of this link is so located that when the push rods are in position to engage their sockets 87 it is in alinement with the lower part 104^x, thus a direct thrust is obtained on movement of the table 112. When power is applied to the treadle lever 106 to move table 112 and thus actuate all four push rods, the sleeves 388 are first moved against their upper collars 386 which moves the links 390 and 400 to bring the push rods 88 and 104 beneath the sockets 87 and extending in the direction of their lower parts 88^x and 104^x. Further pressure on the treadle moves the guide rods 384 upwardly during which movement the sockets 87 are engaged by the push rods and the gripper jaws are all simultaneously closed.

When the treadle 106 is released after corrugating the upper at the toe of the last and after stretching the upper transversely,

the lower portions of all the push rods fall, of their own weight, with the table 112 upon which they rest, carrying with them the sleeves 388 until they are stopped in their downward movement by the lower collars 386 at which time the upper portions of the push rods have been moved outwardly until they are free of the sockets 87 through the action of the links 390 and 400 moving said upper portions about their pivots upon the guide rods 384. Of course it will be evident to one skilled in the art that the features of structure thus described are susceptible of alteration, and in fact many changes may be made therein within the spirit of the present invention, though the mechanism described is found to be well suited to the mechanical results sought.

It is obvious that the push rods 88 and 104 for closing the grippers must be operated to close the grippers before the actuating rods 176 and 178 can be actuated for bringing the gripper carriages down their curved guides in the operation of placing the upper about the last and adjacent the insole. In order to provide against movement of the actuating rods while the push rods are in engagement with their sockets 87, I prefer to arrange the treadle 402, controlling the clutch on the start and stop motion, with relation to the push rod treadle 106 so that the former cannot be moved to place the clutch in action without moving the latter to retract the table 112 sustaining the push rods, and vice versa, when the push rods are moved into engagement with the sockets 87 the lever 402 is necessarily moved in a direction contrary to that for throwing the clutch into action. The preferred arrangement for effecting this result, in this embodiment of the invention, is shown more particularly in Fig. 1. As heretofore described, the treadle lever 106 is preferably pivoted to the frame between its ends at 108. The treadle lever 402 is preferably pivoted to the frame by one end 404 and carries between said pivotal point and the treadle end a stud 406, which projects across and above the lever 106 at a point on the opposite side of its pivot from its treadle. With this construction when the treadle lever 402 is moved downwardly to throw the clutch into action the pin 406 bears upon the lever 106 at such a point with relation to its pivot that the table 112 is retracted allowing the push rods to fall and be thrown outwardly if they were in their upward position. Conversely a movement of the lever 106 to force the push rods upwardly to close the grippers will necessarily engage pin 406 on the lever 402 and move the lever in a direction contrary to that for throwing the clutch into action.

It will be understood that the operations described have been upon a last which has

been so positioned upon the machine with relation to the grippers, that when the upper is placed within the grippers as they stand about the last support and they are closed 5 on the upper and it is stretched, movement of the gripper carriages in their curved guides will necessarily place the upper about the last, and adjacent the insole in position for securing thereto, with the tip line of 10 the upper properly alined across the last and correctly located with respect to the tip of the toe of the shoe. One means for insuring this result is to so position the last upon its support in its final position, just 15 prior to placing the upper about the curved portion of the toe, that an imaginary, correctly located tip line on the last will extend between two longitudinally fixed points, one on each side of the support. Then if the 20 real tip line on the upper be superposed on the imaginary tip line just mentioned and the upper is then secured in place it will necessarily be correctly positioned on the finished shoe. Two convenient longitudinally 25 fixed members are the side grippers, and they may readily be used to aid in positioning the tip line on the shoe. Obviously if the ends of the real tip line are placed between said grippers, each end in the same 30 position relatively to the width of the grippers, and the last is then moved to a position beneath the upper, with its imaginary tip line extending between the same points on the side grippers as determine the position 35 of the real tip line, on moving the grippers about the last in a plane such that their relation to the tip of the toe remains unchanged, the upper will be placed on the last with the tip line of the upper coinciding 40 with the correct, though imaginary, tip line on the last and will be in correct position.

In the present illustration of the invention, when the last is initially positioned 45 upon the machine, the side grippers are preliminarily adjusted, as will be hereinafter explained, to positions about opposite the ends of the tip line of the upper as the upper extends loosely over the last. At this 50 time the tip line of the upper is a greater distance from the tip of the toe of the last than is correct, that is, the tip line on the upper and the imaginary tip line on the last do not coincide. The ends of the tip 55 line may, however, be correctly located, similarly, with relation to the grippers on each side of the last by placing the tip line of the upper in the same position relative to the grippers on each side. The best results 60 in stretching the upper transversely are obtained, in practice, by seizing the sides of the upper with the tip line substantially centrally of the width of the jaws and I prefer to so seize it. To aid in thus placing 65 the tip line within the jaws, one of each

pair, as here shown the upper jaw, is provided with an index line 631 (Fig. 51) preferably parallel to the side edges of the gripper, but which may be otherwise disposed if desired.

When the last is moved forwardly of the machine or heelward, as has been previously explained, the movement is continued until the imaginary and real tip lines coincide. The time when this coincidence occurs is made known to the operative through movement of the tip line gage 156 heretofore mentioned. The gage should be so mounted that when the last is being moved heelward within the upper it will take a position just above the toe and adjacent the upper, while when a shoe is being placed in or taken from the machine it will be withdrawn to a position where it will not interfere with the free action of the operative in either of these operations. I prefer to place and withdraw the gage automatically. The preferred construction for this is best shown in Figs. 2, 3, 6 and 8. Referring to said figures, the link 122, 70 carrying the stop 52, has depending therefrom a hanger 542 which supports a pin 543 in any suitable manner, said pin carrying a sleeve 544 provided with an arm 545. The hanger also has pivoted upon it a bell crank 75 lever 546 one arm of which is connected to the arm 545 by means of a link 547. The other arm of the bell crank carries a roll 548 and this arm is maintained normally in depressed position and in contact with a cam path 549, having high and low portions, by a spring 550 which may be mounted on the bell crank pivot. The cam path is sustained by or may be a part of, the machine frame. A here shown it is a separate member mounted on the toe block 18. The end of pin 543 is headed and from the head projects a second pin 551 at an angle thereto on which is suitably confined a second sleeve 552 having a ball ended arm 110 553 the ball end of which enters a recess 554 in the sleeve 544 forming a ball and socket joint. The sleeve 552 also carries, at an angle to the arm 553, a second arm 555 which projects over the shoe and carries at 115 its free end the tip line gage 156. The gage is preferably made adjustable longitudinally within a sleeve on the carrying arm 555, and is held in position with relation to the toe stop 52 for any desired length of tip, 120 by a set screw 556. The operation is obvious. When roll 548 rests on the high portion of the cam path 549 the sleeve 545 is rotated in a direction to maintain the gage 156 off of and away from the upper, but 125 when the roll rests in the low portion of the cam path the sleeve 545 is rotated in such direction as to bring the gage into measuring position upon the upper. When the toe stop 52 is in its initial or rearward 130

position ready to receive the shoe the roll rests on the high part of cam path and the gage is therefore raised and not in position to interfere with the placing of the shoe in the machine. In practice the last will ordinarily be moved heelward by the toe stop substantially a uniform distance and the cam path is preferably so designed that the gage will be dropped into measuring position upon the upper before the last has been moved far enough for the gage to meet the tip line. The depression in the cam allows sufficient longitudinal movement while the gage is down to insure that the gage will be in measuring position when the imaginary tip line on the last is drawn beneath the tip line of the upper. When the toe stop 52 is withdrawn from the toe of the last and drawn within the edge of the last by the spring 192 the roll is again placed upon a high part of the cam path and the gage is thereby retracted from the shoe so that it does not interfere with the withdrawal of the shoe from the machine. The movements just described are carried forward automatically as the various mechanisms of the machine pass through their regular cycles in pulling over an upper.

As heretofore explained, when a last is placed upon the machine the toe positioning stop 52 is in its rearward position and holds the tip of the toe of the last preferably beneath the inner edges of the toe gripper jaws, but the side grippers are arranged with their inner edges a little distance away from the edge of the last as it is held in position by the side stops 54. In practice this latter distance may be variable.

In the preferred construction of the side grippers each of the lower jaws 63 is provided on its gripping surface with a convenient form to stop as a pin 63^x (Fig. 52), preferably removable, which when the jaws are closed enters an opening 61^x in the upper jaws 61. These stops are preferably so positioned with relation to the inner edges of the grippers that not more than about three sixteenths of an inch of the upper can be seized, this being, in practice, the amount of upper ordinarily available for this purpose. When the side grippers are provided with these stops they may be mounted to have an initial position closer to the edge of the last than when stops are not used, as, no matter how full an upper may be, more than the correct amount cannot be placed within the jaws. When the stops are not used the inner edges of the grippers are placed, preferably, about five eighths of an inch from the edge of the last, it having been found in practice that this location will allow about three sixteenths of an inch of the upper to be gripped. I prefer to employ the jaws having stops as with the grippers nearer the last the operative may more easily place the up-

per between the grippers and he does not have to stretch or strain it by hand to bring it into proper gripping position upon the lower jaws. If the upper has not been cut correctly and is found to be short the side 70 grippers can be adjusted on their carriages to be nearer the last by loosening the set screws 67, the grippers being forced forward in their slots 64 by the springs 148.

All grippers, both toe and side, when open 75 and at rest at the top of their curved guides are preferably so located that the plane of the face of each lower gripper jaw is somewhat above the plane of the top of the support for the ball of the shoe. When so located the upper 80 can be more easily placed upon the lower jaws of the grippers and when so placed lies in substantially a single plane parallel to the bottom of the last. In practice the plane of the faces of the lower jaws of the grippers 85 is preferably a sufficient distance above the plane of the ball support, so that at the time the gripper jaws are closed upon the upper it touches, if at all, only the top of the curved toe portion of the last and not the 90 curved surfaces at the sides of the toe portion of the last. This is particularly advantageous as the upper may now be stretched while it lies in substantially a single plane, and friction incurred in stretching the upper after it has been brought tightly around the curved surface of the last, as has heretofore been the practice, is entirely eliminated, the present invention thus operating on a distinctly different mechanical principle 100 than theretofore. While in this position the upper may be evenly stretched and positioned in a transverse direction from each side of its center line, and longitudinally in the direction of its center line practically 105 without interference from friction.

After the upper has been stretched and positioned both longitudinally and transversely the inner edge of all grippers, after having been initially set in the manner hereinbefore set forth, are about the same distance from the edge of the last. As the vertically arranged curved guides down which the gripper carriages move are preferably all of the same radius of curvature and as their centers have substantially the same relation to the edge of the last in each instance, there should in each case be about the same amount of upper available to be brought within the edge of the last after the grippers have been moved down their curved guides to place the upper about the curved portion of the toe of the last.

As illustrated by Fig. 58 when a line *a a*, 125 is passed at right angles through the center of a line *b b*, corresponding to the imaginary, correctly located tip line of a last, when said tip line is placed square across the shoe, as is generally customary, the central points *c* of the toe and *d* of the heel are 130

both at the left of the line a for a right last and such points c , d , respectively are at the right of said line for a left last. If the heels of the two lasts were superposed one on the other the toe part of each would extend at a considerable angle to the line b b . This deflection from a straight line is termed the "swing" of the last. When a last is placed relative to a line b b as shown in Fig. 58 the heels are moved to a position off of the line b b . For convenience I will hereinafter term the deflection at both ends of a last positioned as in Fig. 58, a "swing." For different sizes of the same style of last the increase or decrease of the swing will be constant, but the amount of this swing may, however, be different in different styles of lasts. In this embodiment of the invention, a line corresponding to the line a a would coincide with the center line of the machine since the grippers are located equidistantly from the center line and since a line between the grippers corresponds to the tip line on a finished shoe. Hereinafter, a line corresponding to the line a a will for convenience be termed the "machine center line," but it is obvious that machines could be constructed embodying the principles of this invention wherein the line a a and machine center line would not coincide and therefore the term should be read as one of designation only. With this nomenclature it is obvious that when the imaginary tip line on the last is placed in coincidence with the real tip line on the upper, the centers of the toes and heels of different sizes and styles of lasts will project for varying distances on either side of the machine center line. This being the case, in the form of machine described, means are provided for adjusting the position of the grippers about the last, and with relation to each other or to the machine center line, so as to correctly pull over the upper on either a right or left hand last of any size and on different styles of right and left lasts. The preferred mechanism for performing this function, to be used with this embodiment of the invention, is best illustrated in Figs. 2, 4, 6, 7 and 14. As there shown a lever 408 (Figs. 4 and 7) is mounted on a short rock shaft 410 suitably journaled in the head 4, which rock shaft also has secured to it an arm 412 carrying at its upper end a beveled gear segment 413. Meshing with this beveled gear segment is a second beveled gear segment 415 on one end of a transverse arm 414 pivoted at its other end at 416, on the central bracket 16, said pivotal point being upon the longitudinal center line of the machine. The arm 414 has pivoted to it a link 418, extending longitudinally of the machine, and having pivoted upon it a second link 420 (Fig. 7), each of said links being connected adjustably to one arm of bell crank levers 422 and 424 respectively, which levers may be both pivoted on the same pin 426 on a stationary part of the frame. This construction allows of adjustment between either link and its bell crank lever independently of the other. Movement of one of these bell crank levers operates to move the curved guide 12 carrying the toe gripper supports bodily transversely of the machine, so that the central point of said toe grippers may be placed upon one side or the other of the center line of the machine to accommodate them to the swing of a right or left shoe (see Fig. 5). Movement of the other of said bell crank levers operates to change the relative position of the stops 272, in the ends of curved guide 12 and against which the toe gripper carriages abut when they are moved outwardly in said guide by extension of the toggle 256, according to whether a right or left shoe is being operated upon.

Referring again to Fig. 58, it is seen that with a right last there is a greater angle between the edge of the last at the end of the tip line at the right of the line a a and said line, than between the edge of the last in a similar position at the left and said line, and vice versa for a left last. Under these conditions, when pulling over a right shoe, the stops 272 should be so positioned in the ends of curved guide 12 that the toe gripper support at the left, facing the machine, may be moved through the greater angle necessary to bring the inner edge of its grippers in parallelism with the edge of the last, than the toe gripper support at the right, and vice versa when pulling over a left shoe. The movement of the toe grippers bodily transversely of the machine, however, will obviously be the same for either a left or right shoe of the same style.

A movement of the grippers bodily transversely of the last will first be described. As herein shown, this movement is obtained by actuation of link 420 and its bell crank lever. The other arm 423 of this bell crank lever is pivoted to one end of a link 428 (Fig. 7), the other end of which is pivoted to a transverse slide 430 having movement in gibbs 432 formed upon the rear bracket 6 (Fig. 14). This slide 430 has mounted thereon the longitudinally arranged guides 10 between which the table 8 carrying the circular guide 12 slides, the guides 10 having mounted thereon the circular slide 248 for the blocks 250 as heretofore explained. Thus, actuation of the link 420 will rock its connected bell crank about the pivot 426, throwing the arm 425 of said bell crank in one direction or another for moving the slide 430 transversely of the machine and with it the toe gripper supports, the universal connection 268 between the arm 246 of the bell crank lever 244 and the socketed block 260 preventing any binding of the 180

parts during such movement. To adjust the stops 272 I prefer to use a second slide 436 (Fig. 14), which may be guided in ways 434 formed in the bracket 6 sustaining the sliding table 8, this slide having connected to it one end of a link 438 (Fig. 7), the other end of which is pivoted to the other arm 425 of the bell crank lever 424. To each of the stops 272, which may be mounted in short 10 guide ways 273 in the bottom of the curved guide 12, is pivoted one end respectively of extensible links 440, the other end of said links being pivoted to the slide 436 at equal distances from its center. It is thus seen 15 that a movement of the lever 408 in either direction will through its connections to the transverse slide 436, actuate the links 440 to move the stops 272 in their guide-ways 273 and place them in correct position to stop 20 the outward movement of the toe gripper supports when the grippers reach a point where their inner edges are in parallelism with the sides of either a left or right last. For regular styles of shoes these links 440 25 are of the same length, but for "freak" or "outside" styles, as they are termed, it may be necessary to adjust them, making one or the other longer or shorter as may be necessary so that when the stops 272 are adjusted 30 the toe gripper supports will be stopped, after moving outwardly, in correct position for the style of shoe being operated upon.

At the same time that the toe gripper supports are moved transversely of the machine 35 to change their position for working upon a right or left shoe the toe positioning stop 52 should also be given a transverse movement, so that when the last is placed upon the machine its toe may be correctly positioned 40 with relation to the new location of the central point of the toe grippers. In the particular construction herein illustrated this is preferably accomplished by mechanism shown more particularly in Figs. 4, 6 and 7. 45 As there shown the toe block 18, which carries the support 21 for the ball of the shoe and the toe positioning stop 52, is pivoted at 19 (Fig. 4) on the central bracket 16, the pivot lying upon the center line of the machine, and a curved gib 17 is mounted upon the bracket 16 in position to guide the forward end of the toe block. The toe block 18 is also provided with a tail piece 442, which preferably has a forked end (Fig. 7) adapted 50 to engage a pin carried by an arm 445 projecting rearwardly from the inner end of the arm 414 which carries the beveled segment 415. It is readily seen that as the lever 408 is moved in a direction to throw 55 the central point of the toe grippers to the left of the center line of the machine the same movement will throw the tail piece 442 of the toe block 18 to the right of the center line of the machine. Consequently the toe 60 positioning stop 52, which is on the opposite

side of the pivot 19 from the tail piece 442 is also thrown to the left of the center line of the machine. Similarly a movement of the lever 408 in the other direction will throw the central point of the toe grippers 70 and the toe positioning stop 52 to the right of the center line of the machine. In either case, the center of the toe positioning stop 52 is moved substantially the same distance to the right or left of the center line of the machine as the central point of the toe gripper edges, and, as heretofore explained, at the time the gripper jaws are closed upon the upper these two points are in substantially vertical alinement, so that after this 80 adjustment has been made there is no question but that when a last, either right or left, is placed in the machine the tip of its toe will be correctly positioned with relation to the toe grippers. As the tip line gage 156 is 85 mounted upon the link 122 it is carried with the toe stop as it moves to one side or the other of the machine.

Owing to the angularity of the sides of the last with relation to the center line, as 90 heretofore mentioned, it is desirable to place the side gripper supports in angular relation to the center line of the machine in order that the inner edges of the grippers will be parallel with the sides of the last, 95 to insure that as their carriages are moved down the curved guides in the supports the upper will be correctly and snugly brought around the curved portions of the last in the operation of placing the upper about the curved portion of the toe of the last. Owing to the difference in angularity of each side of the last (see Fig. 58), each of the side supports when so positioned will be at a different angle to the center line of the 100 machine, the angle of the side gripper support at the left of the shoe being greater than that at the right of the shoe when the right shoe is being operated upon, and vice versa when a left shoe is being operated 105 upon. I preferably provide means for placing the side gripper supports in their proper angular relation for a right or left last, controlled by the movement of the lever 408, so that as this lever is moved to adjust other 110 parts of the machine in correct position for the shoe to be operated upon the side gripper supports will automatically be brought into such angular relation with the center 115 line of the machine that the inner edges of the side grippers will be parallel to the edges of the last. In the illustrated form of the invention, the mechanism which I prefer to use is best shown in Fig. 6. In order 120 that the side gripper supports may have angular movement their supporting blocks 56 are pinned to the rotatable guide rods 220 which thus form fulcrum for said supports. The outer ends of the blocks 56 are 125 constructed to slide under curved gibs 446, 130

and are thus guided in their movement about the fulcra 220. The side gripper supports 58, sustained by the blocks 56, are held forwardly by any convenient means as 5 springs 448, against stops 450, which form one arm of bell crank levers 452 fulcrumed on pins 453 on the frame 14 equidistant from the machine center line and with their angles pointing in opposite directions. The 10 other arms of these bell crank levers are connected transversely of the machine by a yoke 454 which is provided at one side with a slot 455 forming a loose connection for a roll 456 carried by an extension 457 of the 15 arm 414 on the other side of its pivot 416. As the bell crank levers 452 are alike, when lever 408 is in its central position, that is, with the arm 414 at substantially right angles to the center line of the machine, the 20 stops 450 are both equidistant from the fulcra 220 of their respective side gripper supports 58. When, however, lever 408 is moved out of its central position the yoke 454 is moved to the right or left through its 25 connection with the extension 457 of arm 414 and the arms of the bell crank levers 452 forming the stops 450 are thrown to the right or left, as the case may be, for a left or right shoe respectively, which changes 30 the relation of the stops 450 with respect to the fulcra 220 of the side gripper supports, so that one is nearer to its side gripper support fulcrum than the other. When in this position the side gripper support having 35 one of the stops 450 nearest to its fulcrum will be moved to a greater angle with the center line of the machine than the other side gripper support, as is correct, as heretofore explained, owing to the difference of 40 angularity between the sides of the last and the center line. The side gripper supports are maintained in whatever position they are placed by the movement of bell crank levers 452 through the springs 448 which 45 keep them in contact with the stops 450. It is thus seen that when lever 408 is moved to shift the toe grippers for a right or left last the side gripper supports are simultaneously and automatically moved to angular 50 positions with relation to the center line of the machine, the proportions of the parts being such that for the regular or ordinary styles of lasts this angular movement will place the inner edges of the side grippers in 55 parallelism with the sides of the last. For "freak" styles the angles are altered as may be required by moving lever 408 through different angles as will be hereinafter explained.

60 When working upon a series of right and left shoes of the same size and of the same width no preliminary adjustment is necessary for width when adjusting to pull-over a right or a left, but if a different width of shoe is to be operated upon the side grippers

must be moved outwardly for wider shoes to give a greater space between the inner edges of the grippers, and for a narrower width of shoe they must be moved inwardly to lessen the space between the inner edges 70 of the grippers, in other words, the space between the grippers should be adjustable so that the space between their inner edges and the edge of the last will remain constant, no matter what the width of the last. 75 In the illustrated embodiment of the invention I prefer to use the mechanism illustrated in Figs. 7 and 8 to gain this adjustment. As there shown the side gripper supporting blocks 56 are each mounted upon a 80 transversely movable slide 458 guided in ways 459 on frame 14. These slides also carry the curved gibs 446. Conveniently mounted on the frame 14 is a stud 460 which carries loosely upon it a disk 462 provided 85 with peripheral teeth 464. Also mounted upon the stud 460, so as to have movement with relation to the disk 462, is a controlling lever 466 provided with a spring pressed 90 detent 467 adapted to enter between the teeth 464. Mounted upon the handle 466 at its pivotal point is a cross bar or centrally pivoted lever 468 provided with studs 469 and 470 at its ends. From these studs 469, 470 extend links 471, 472 respectively, the other 95 ends of said links being pivoted at 473, 474 respectively to the slides 458, said pivotal points being equidistant from the center line of the machine. A link 476 is pivotally connected at one end to a wrist pin 477 on 100 the disk 462 and at its other end to a stationary part of the frame, and thus normally holds the disk from movement on its stud 460. The function of this link will be explained hereinafter. With the construction 105 just described, it is seen that a movement of hand lever 466 in one direction will move the cross bar or lever 468 with relation to stud 460, which movement will push upon one of the links connected to the slides 458 and pull upon the other, so that the slides will be moved, say, away from each other, enlarging the space between the inner edges of 110 the side grippers and a movement of the hand lever in the other direction will move the links in such directions as to draw the slides 458 together narrowing the space between the inner edges of the side grippers. As the pivot pins 473, 474, connecting links 115 471, 472 to the slides 458 are equidistant from the center line of the machine, movement of the slides 458 in either direction will be uniform, as is necessary, for the reason that as lasts increase in width from the same size, the increase is equal on each side 120 of the center. With this construction, if it is desired to adjust the machine for operating upon a wider or narrower shoe of the same size that the machine has been previously pulling over, it is merely necessary to 125 130

move hand lever 466 so as to adjust slides 458 either inwardly or outwardly to bring the side grippers to the position desired.

It should be noted that for every increasing width of last of the same size the angles formed by the sides of the last, as heretofore mentioned, will also increase, and therefore the angularity of the side gripper supports 58 with relation to the center of the machine should be altered to correspond to the changed angularity of the sides of the lasts in order that the inner edges of the grippers may be kept in parallelism with the side edges of the last. This is taken care of automatically by the mechanism heretofore described for changing the angular relation of the side gripper supports for rights and lefts. As the slides 458 carrying the side gripper supports 58 are moved, say, outwardly for a wider last the fulcra 220 are brought nearer to the stops 450 on the bell crank levers 452 which remain stationary, and thus as the slides 458 move outwardly said gripper supports 58 will be moved about their fulcra, owing to the contact maintained between the sides of said supports and the stops 450 by the springs 448. The angle is similarly changed in a reverse direction when the slides 458 are moved inwardly for a narrower last.

Of the main preliminary adjustments for correctly positioning the grippers about the last, so that when they are closed upon the upper and moved downwardly in their curved guides the upper will be properly pulled over, there remains to be described the adjustment for change of size. As the toe positioning stop 52 and the toe grippers preferably have a single initial position for all sizes of lasts, the machine forming this embodiment of the invention is adjusted for different sizes of lasts by movement of the heel block 24 which sustains the heel support. In making lasts, when the size of the last is increased the width is also increased although the two sizes may have the same width letter, that is, a last "size 4, width B" is wider than a last "size 3, width B." Also, for each increasing size of shoe the tip lengthens and therefore the tip line in correct position is farther from the tip of the toe of the shoe. Therefore, in adjusting the machine for longer lasts of the same width as the last previously operated upon, it is not only necessary to increase the distance between the toe positioning stop 52 and the heel support, to accommodate the greater length of last, but the slides 458 carrying the side gripper supports should be moved outwardly to allow for the increase in width of the shoe, the frame 14 carrying these slides 458 should be moved forwardly to correctly position the side grippers with relation to the greater length of tip, and the tip line gage 156 should be moved farther from the toe stop

52. These movements would all be reversed when adjusting the machine for a smaller size of last than that previously operated upon. The mechanism which I prefer to use to perform this adjusting operation is best shown in Figs. 3, 4, 6 and 7. Referring to these figures, a short shaft 478 is suitably journaled at one side on the frame of the machine, which shaft is rocked through a lever 480 secured thereto, said shaft also being provided with an arm 482 having a beveled gear segment 483 (Fig. 7) which meshes with a second beveled gear segment 485 which may be carried by one end of a link 484 pivoted at 486 between its ends to a stationary bracket. A similar link 488 is pivoted at its outer end to a stationary bracket 489 on the other side of the machine. The inner ends of these two links are pivoted together by means of a pin 490, they being of sufficient length to form a toggle joint extending transversely of the machine frame. The pin 490 has also pivoted to it one end of a link 492 (Fig. 4) extending longitudinally of the machine, its other end being pivoted to the heel block 24, this link forming a movable connection between the toggle and heel block. Each of the toggle links 484, 488, is connected to the sliding frame 14 by means of longitudinally extending links 494 pivoted at one end to the toggle links and at their other ends to forwardly extending brackets 15 (Figs. 4 and 6) on the sliding frame. By means of the connections just described, it is seen that upon movement of lever 480 in one direction, through the toggle 484, 488, the heel block 24 sustaining the heel support is drawn forwardly in its guides 22, and with it, by means of the connecting links 494, the transverse sliding frame 14 which carries the side gripper supports. This movement of heel block 24 will increase the distance between the toe positioning stop 52 and the back 41 of the heel support, and the movement of the frame 14 will increase the distance of the side grippers from the tip of the toe of the last, these grippers, as heretofore explained, governing the distance of the tip line of the upper from the tip of the toe of the last. The movement of frame 14 will also carry the disk 462 (Fig. 7) with it bodily, and owing to its connection through the wrist pin 477 and the link 476 to a stationary part of the frame, as heretofore described, this disk is rotated carrying with it the lever 468, thus automatically moving the slides 458 outwardly through actuation of the links 471, 472. A movement of the lever 480 in a reverse direction to that just described will move the heel block 24 and the frame 14 rearwardly, and the side-gripper support-carrying slides 458 inwardly, as will be readily seen.

The adjustment of the tip line gage 156 to the new length of tip is effected, prefer-

ably automatically. The preferred mechanism for use with this embodiment of the invention, is shown most clearly by Figs. 2, 3, 6 and 8. As there shown the pin 543 is supported on the hanger 542 by being secured to one arm of a bell crank 580 which may be pivoted on the same stud that sustains the bell crank 546. The other arm of the bell crank 580 carries a roll 582 adapted to engage a member 584. This member is preferably slotted and extends longitudinally of the machine, the roll 582 riding within the slot so that when the toe stop 52 is moved forwardly the bell crank 580 will not be rocked and thus alter the relation of the gage and toe stop. Movement vertically of the member 584 will rock the bell crank 580 and such movement will move the carrying arm 555 of the gage bodily longitudinally of the machine with relation to the toe stop 52, thus changing the length of tip that will be gaged. The pivotal connection between arm 545 and link 547 will take up this movement so that the vertical relation of the gage to the upper is not altered. Any convenient means may be used for transforming the longitudinal motion of the frame 14 into vertical motion of the slotted member 584. As the slot should be maintained parallel to the path of movement of the roll 548 on its forward movement I prefer to employ two bell cranks 586 pivoted on a stationary part of the frame each having an arm connected to the member 584 and their other arms connected by links 588 to a lug 590 on the frame 14. Obviously any movement of the frame longitudinally will rock the bell cranks 586 to move the member 584 vertically and the gage 156, in turn, longitudinally.

Owing to the fact that it is desirable, in this embodiment of the invention to keep the toes of all sizes of right lasts in a single initial position longitudinally and the toes of all left lasts in an analogous single initial position, (shown diagrammatically by Fig. 58), and to the fact that when so positioned the heel of a right last must have a deflection or swing to the left and the heel of a left last must have a deflection or swing to the right, in the sense as hereinbefore explained, as the heel standard 26 is moved to increase or decrease the distance between the heel support and toe positioning stop it should be guided in a line having the same angular relation to the longitudinal center line of the machine as the swing of the last being operated upon. To gain this end, as here shown I prefer to provide the arm 414, which is actuated from the right and left controlling lever 408, with a forwardly projecting slotted member 500 (Figs. 4 and 7), the rear end of the slot being preferably directly above the pivot pin 416. The heel standard 26 is directly sustained by a block

502, movable transversely in guideways 504 (Fig. 4) formed in the heel block 24, and the lower end of the heel standard 26 extends through its sustaining block 502 and through a transverse slot 25 in the heel block 24. This standard carries at its lower end a roll 506 adapted to rest in the slot formed in the member 500. It is thus seen that when lever 408 is moved to throw the center of the toe grippers and toe positioning stop to the left of the center line of the machine in positioning the toe of a right last, the slotted member 500 is also thrown to the left hand side of the center line of the machine about its rear end as a pivot, 80 taking a position having substantially the same angular relation to the center line as the swing of the heel of the last to be operated upon, (see Fig. 6). When the controlling lever 480 is thereafter moved to adjust the machine for a larger size of last and the heel block 24 is moved forwardly in a line parallel to the center line of the machine in its guides 22, the heel standard 26 is guided in its forward movement by the 90 slotted member 500, being carried to one side of the center line as it moves forwardly, this transverse movement being allowed by the transverse slot 25 in the heel block 24 and the movable block 502. By means of 95 this mechanism the heel support is always placed in correct relation to the toe positioning stop 52, no matter what size shoe is to be pulled over, whether right or left.

In pulling over shoes I prefer to so position the last that its ball rests firmly upon the wings 21 forming the ball support. With different sizes of lasts the curvature under the shank from the ball line to the heel will vary and therefore the vertical distance between the plane of the ball of the last and the plane of the heel seat will vary. This distance will also vary with different styles of lasts of the same size. To insure positioning the last as is desired means should be provided for varying the vertical distance between the ball support 21 and the heel rest 40. To gain this end I prefer to make the heel support adjustable upon its standard as is best illustrated in Figs. 2 and 3. As there shown the sleeve 28, which carries the entire heel support, is given free motion vertically on the standard 26 and is provided with an arm 530 on which is a roll 532. This roll rides within a slot 534 of a bar 536 extending longitudinally of the machine and suitably supported upon the frame of the machine, as by standards 538. Each end of the bar 536 has a slotted connection 540 with its respective standard so that the angular relation of the bar to the heel standard 26 may be altered at will. With this construction, as the heel standard is moved in either direction by lever 480 to adjust the heel support for a different size of last the roll 532 travels

up or down the slot 534 and the heel support will be raised or lowered as it moves longitudinally. The variation in the distance between the planes of the ball and heel seat of a last, for each difference in size, is constant on any particular style and therefore by changing the angle of the bar 536 it will automatically and correctly vary the height of the heel seat member 40 with respect to the ball support 21 for any style of last when the machine is adjusted for size.

It is sometimes desired to provide the finished shoe with an abnormal length of tip, and therefore in the illustrated embodiment 15 of the invention I have provided mechanism for supplying the shoe with an abnormal length of tip without altering the adjustment of the machine with relation to the length of the last being operated upon. Referring to Figs. 4, 6 and 7, in the preferred construction of this mechanism the brackets 15 of the frame 14 are each provided with a transverse guideway 508, in each of which is slidably mounted a hollow block 510, these 25 blocks being connected for simultaneous movement by a rod 511. It is to these blocks 510 that the rear ends of the links 494 are preferably connected. To this end the rear ends of the links 494 are provided with pins 30 512, which pins extend through diagonally arranged slots 514 in the hollow blocks 510 and into longitudinally arranged slots 516 in the brackets 15. The pins 512 carry rolls 515, which lie within the diagonal slots 514. 35 One of the brackets 15 is provided with an auxiliary bracket 518 (Figs. 6 and 7) which carries a disk 520 having teeth 521. Mounted to have movement relatively to the disk 520 is a bell crank lever, one arm of which 40 forms a handle 522 carrying a spring pressed 45 detent 524 adapted to engage the teeth 521, and the other arm of which is loosely connected at 526 to the end of a rod 528 carried by the adjacent hollow block 510. With this 50 construction a movement of handle 522 in one direction will move the hollow blocks 510 transversely of the machine in their guideways 508, and as the links 494 are held from any transverse movement about their pivotal 55 connections to the toggle links 484, 488, by the ends of the pins 512 projecting through the slots 516 in the brackets 15, the rolls 515, in effect, are made to travel along the diagonal slots 514 in the hollow blocks, thus moving 60 the entire frame 14 longitudinally of the machine. This movement alters the longitudinal position of the side grippers which govern the position of the tip line as heretofore explained. As the length of tip is increased or diminished the side grippers should be moved outwardly or inwardly, respectively, to take care of the greater or less width of last at the new tip line. This 65 movement of the side grippers is taken care of automatically when the frame 14 is moved

longitudinally of the machine through the connection of the link 476 to the disk 462 as heretofore explained.

As the toe gripper supports are moved transversely of the machine for right and 70 left shoes they carry with them the gripper carriage actuating rods 178, and as the side gripper supports are moved longitudinally of the machine for different sizes of shoes and transversely of the machine for different widths of shoes, they carry with them the gripper carriage actuating rods 176. As these rods are actuated simultaneously by the cam 162 through the rod 172, means should be provided to allow movement of the 80 lower ends of the actuating rods upon the rod 172 during the various adjustments above mentioned. In the illustrated embodiment of the invention to gain this end I prefer to construct the head of the rod 172 as 85 shown in Figs. 8 to 13. As there shown, the rod 172 has a head 558 (Fig. 10) which is provided with a longitudinal opening 559 and a pair of pins 560 extending transversely from the head, one on each side. 90 Within the slot or opening 559 rests a pin 562 which is of less width than the slot (see Fig. 13), said pin having at its rear end a sleeve 564 loosely surrounding a vertically arranged guide rod 566 supported from a 95 yoke 568 depending from the circular guide 12 (Fig. 10). Surrounding the sleeve and suitably held in position thereon are two loose collars 570 and two arms 572, carried by these collars are pivoted one to each of the lower ends of the toe gripper-carriage actuating rods 178. On each of the transversely extending pins 560 of the head 558 is a loose sleeve 574 (Figs. 11 and 12), each of these sleeves being also provided with an 100 opening through which pass the rods 220 forming the fulera of the side gripper supporting blocks 56, and on these rods are suitably confined loosely mounted collars 578. On pins 579 projecting from these collars are swiveled the lower ends of the side gripper-carriage actuating rods 176. With 105 this construction, when the circular slide 12 carrying the toe gripper supports is moved transversely of the frame to position the toe grippers for a right or left last, the actuating rods 178 are necessarily carried with the supports, and in this movement the yoke 568 for the guide rod 566 is also moved, carrying the rod with it and moving the pin 562 across its slot 559, as shown in Figs. 11 and 13, without imparting any transverse movement to the rod 172 which carries the head 558, although keeping the parts in position to be actuated by said rod 172 when the cam 162 rotates. As the toe gripper supports are thereafter moved outwardly in their curved guide 12, still carrying the actuating rods 178 with them, free motion 110 is allowed about the guide rod 566 by move- 115

ment of the loose collars 570 to which the actuating rods are pivoted. In the same manner, when the slides 458 carrying the side gripper supports are moved transversely of the frame for different widths of lasts, the sleeves 574 slide upon the transverse pins 560 carried by the then stationary head 558. Movement of the side gripper supports about their fulcra 220 in bringing the side grippers parallel to the edges of the last will be perfectly free, because of the loose connection of the actuating rods 176 on the rods 220 through the loose collars 578. When the frame 14 is moved longitudinally of the last for different sizes of shoes, the head 558, carrying with it the actuating rods 176, is moved longitudinally upon the pin 562 as a guide. The rod 172 moves with the frame 14, as it is supported therefrom, as heretofore described, and the arm 166 carrying the cam roll 164 moves about the shaft 158 as a pivot, such movement being allowed through the pivotal connection to block 170 (see Figs. 1 and 10). This motion of the roll 164, however, is never sufficient to interfere with the correct operation of the cam. The right and left controlling lever 408 is provided with means to lock it in one position or the other and it is desirable to make such means adjustable so that the throw of the lever may be readily altered to correctly set the parts to position different styles of shoes. My preferred construction for use with this embodiment of the invention is shown most clearly in Figs. 3, 4 and 6. Referring to said figures, mounted on the journal of the rock shaft 410 is a bracket 592 having a segment top 593. This segment is channelled longitudinally and in the channel are two blocks 594 each provided with a beveled projection 596 and shoulder 598 forming between them a recess. The shank of the controlling lever has mounted thereon a spring pressed detent 600 which when the lever is moved will ride up one or the other of the beveled projections 596 and seat itself in one of the recesses, thus locking the lever in the position to which it is thrown. In order to alter the amount of throw the blocks 594 are made adjustable on the segment 593. The channel in the segment top is provided with a slot 602 at each end and the blocks 594 are held at any desired point in their respective slots by clamping screws 604. By adjusting the blocks 594, the connection between the links 418 and 420 and their bell cranks 422 and 424, and the length of the links 440 carrying the stops 272, the machine may be set up to accommodate a right or left shoe of substantially any style.

The size controlling lever 480 is provided with a convenient locking means and scale to aid the operative in quickly setting the machine. Referring to Figs. 3 and 6, showing a preferable construction, a bracket 608

is mounted on the journal of the rock shaft 478. This bracket sustains a segment 610 provided with teeth adapted to be engaged by a spring pressed detent 612 carried by the shank of a lever 480. The segment is also preferably provided with a scale to indicate the proper amount of movement to be given lever 480 to set the machine for the required size of shoe. Frequently a given size of one style of shoe will be equal to a quarter or half size larger or smaller than the same given size of another style of shoe and it is therefore desirable to provide means for adjusting the scale with relation to the controlling lever so that the figures on the scale denoting a particular size may be used with the new standard of measurement. To this end, I preferably provide a guideway for the segment 610 on the bracket 608, for instance a mortise and tenon 614, and pass a clamping screw 616 through the segment and through a slot in the bracket. The scale is thus easily adjusted for different standards of size.

The controlling lever 466 is also provided with a scale 620 indicating the various widths of shoes, and this scale is preferably mounted so as to be adjustable with relation to the lever similarly to the scale for the lever 480, and for the same reasons.

In pulling over a shoe with the machine illustrated in the accompanying drawings, the operative first sees that the hand lever 138, which operates to withdraw the link 122, carrying the toe stop 52, is in such position that the toe stop extends rearwardly and is substantially beneath the inner edges of the toe grippers. He then examines the last to determine its size and width, and whether it is a right or left and then throws the controlling lever 408 in the proper direction to move the curved guide 12, carrying the toe grippers, and the toe positioning stop 52, to position, with their centers to the right or left of the longitudinal center line 110 of the machine, as may be necessary. In the drawings, I have shown a right last, upon the machine, in dotted outline, and will assume for the purposes of this description that this is the last being operated upon, and therefore the toe positioning stop 52 and the circular slide 12 will have been moved to the left of the center line of the machine. This movement of the lever 408 also moves the slide 436 so as to position the stops 272 in the circular guide 12 with the left hand stop farther from the center of the guide than the right hand stop. This movement of the lever 408 also moves the slotted member 500 on the arm 414 to the left of the center line and the extension 457 of said arm is moved toward the right in the slot 455 of the yoke 454, the bell crank levers 452 being thereby positioned so that their stops 450 are arranged to maintain the right hand side 130

gripper support 58 at a more acute angle to the center line of the machine than the left hand side gripper support. The gripper supports 58 are maintained in contact with the stops 450 by means of the springs 448. The operative then moves the controlling lever 466 a proper distance to bring the side grippers and the side positioning stops 54 the correct distance apart for the width of last to be operated upon. The controlling lever 480 is then moved in the proper direction to bring the heel support to such a position relative to the toe positioning stop 52 as to accommodate the length of last to be operated upon. During this movement of the lever 480 the heel standard 26 carrying the heel support moves in the slotted member 500, the frame 14 moves longitudinally of the machine, these movements not affecting the position of the stops 450 owing to the slotted connection 455, 456, the slides 458 carrying the side gripper supports automatically adjust themselves transversely of the machine and by this movement, the stops 450 remaining stationary, the side gripper supports 58 automatically adjust themselves on their fulcrum 220, to bring the inner edges of the side grippers in parallelism with the sides of the last.

At the same time that the machine is adjusted for size through movement of the lever 480, the heel seat 40 is also adjusted automatically as to its height with relation to the ball support 21, through the roll 532 on the sleeve 28, riding in the slotted bar 536, as hereinbefore explained, so that the last when placed on the machine will rest with its ball firmly seated in the ball support. The last may now be placed against the toe positioning stop 52 with its ball resting upon the ball support 21 and between the side positioning stops 54, and its heel between the arms 44 of the heel support. These arms 44 automatically adjust themselves to the curvature of the sides of the heel portion of the last through the action of their spring 46, and the heel seat 40 turns about its pivot 38 and causes the heel of the last to rest snugly within it by the action of the springs 48. If the shoe is to have an abnormal length of tip, the lever 522 is moved sufficiently to bring the side grippers forward or back longitudinally of the last for the desired distance. As illustrated the last is a normal one, and therefore the rolls 515 carried by the pins 512 in the ends of the links 494 are shown centrally in the diagonal slots 514 of the hollow blocks 510, slidably sustained in the brackets 15 of the frame 14. Any other adjustment for "freak" or "outside" styles are ordinarily made by placing the shoe on the machine and shifting the adjustable parts to suit the particular contour of the edge and position of tip line. These preliminary adjustments

having been made and the last placed in the machine, the upper is seized by the operative at its sides at about the tip line, smoothed out, and inserted within the open side grippers on each side of the last with the ends of the tip line resting beneath the index marks 631 upon the gripper jaws and against the stop pins 632, if such pins are used. The toe portion of the upper naturally extends itself upon the inner faces of the open lower jaws of the toe grippers. As heretofore explained, all of these lower jaws extend about the last in substantially the same plane and preferably a little above the plane of the bottom of the last, so that when the upper has been placed upon said lower jaws it lies in substantially a single plane. Still holding the upper in position upon the lower jaws of the grippers the operative presses the treadle lever 106 and actuates the side and toe gripper push rods 88 and 104 simultaneously through the mechanism described, to close the upper jaws of the grippers upon the lower jaws and thus seize the upper firmly therebetween. A pressure is placed upon the upper by the side grippers equal in amount only to the compressive strength of the springs 120, which sustain the auxiliary tables 118, when said springs are compressed by further movement of the treadle lever 106, but there being no spring interposed between the treadle lever and the toe gripper push rods, continued pressure on the treadle lever will continue to force the toe gripper jaws together upon the upper, and through the transversely-extending corrugations, on these jaws, this pressure corrugates or flutes the upper for a considerable distance about the toe, in such manner that when the upper is placed about the last the stock at the toe will be evenly distributed thereabout. The operative then grasps with one hand, the controlling lever 138 and with his other hand the controlling lever 150 and may simultaneously move these levers to stretch and position the stock both longitudinally and transversely. The longitudinal stretching and positioning of the stock is obtained through moving the last heelward by actuation of the link 122 carrying the toe positioning stop 52, and this movement of the last, which in many instances may with advantage take place slightly in advance of the transverse stretching, is continued until the upper has been brought into such position that the tip line comes beneath the tip line gage 156 which automatically sets itself in measuring position as heretofore explained. Owing to the shape of the cam 142, which engages the lower end 133 of the lever 128, the controlling lever 138 will be maintained in any position to which it is moved.

The stretching of the upper transversely is accomplished by pressure upon the side

gripper push rods 88, thus drawing the side grippers outwardly in the slots 64, in the lugs 62 on the gripper carriages, against the tension of the springs 148, such movement 5 of the push rods operating to move and actuate the levers 76, thus forcing the pawls 82 farther along their ratchets 84 and locking the side grippers in whatever position they are placed by movement of the lever 10 150. By stretching the upper in this manner the straining movement is at all times under the control of the operative, and the upper and particularly its tip line, being at all times in full view of the operative, there 20 can be no question but that the upper will be properly stretched. The tip line must also necessarily be square or otherwise properly aligned across the toe of the last, because of being originally placed on the index 25 marks 631 on the oppositely arranged side grippers. After these operations the upper is so positioned with relation to the last that on placing it about the curved portion of the last the tip line will be correctly located. 30 At this time, as heretofore explained, the inner edges of all the grippers lie substantially the same distance from the edge of the last so that if each pair of grippers is brought downwardly in a curved line which 35 has its center in substantially the vertical plane of the edge of the last, the stretched upper will be placed snugly about the curved portions of the last, and there will in each instance remain substantially the same 40 length of upper to be brought inwardly past the edge of the last and placed adjacent the insole. After the upper has been stretched, the operative releases the treadle 106 and the controlling lever 150, which allows all 45 four of the push rods to fall of their own weight, which may be assisted if desired, by a spring in which downward movement their upper portions are moved outwardly by the mechanism heretofore described, to 50 such position that they will be cleared by the sockets 87, upon the arms 86 of jaw closing actuating levers 76, in their downward movement.

The shoe is now ready to have the gripper 55 carriages moved downwardly in their vertically arranged curved guides to lay the stretched upper about the curved sides of the last and move its margin inwardly to a position adjacent the insole so that it may be 60 secured in place. As heretofore described, when the gripper carriages are in the upper ends of their curved guides each presenter block 332 has been actuated into its forward position and sustains a staple, the heads of 65 which lie just beneath the open catches on the heads 308 of the driver bars 300, which bars lie in a plane substantially parallel to the plane of the staples carried by the presenter blocks, owing to the action of the 70 springs 318, on the carriages, and the pins

316 on the curved guides. At this time also the hammers 274 are held in their retracted position with the springs 278 compressed by means of the latches 286 bearing upon the surface 275 of each hammer. Upon the 75 operative then pressing the treadle 402 the power shaft 138 is thrown into operation to actuate the rods 176 and 178 to move the side and toe gripper carriages down their curved guides. Rotation of the power shaft 80 rotates the cam disks 160 and 208, but the roll 212 at this time is traveling in a dwell of the cam groove 210 formed in the disk 208. The cam groove 162, however, immediately begins to move the roll 164 in a direction to draw downwardly upon the arm 166, to which is secured the rod 172 carrying the head 558 of which the gripper carriage actuating rods 176, 178 are mounted. As the gripper carriages start their downward movement they carry with them the drivers 300, the catches on the heads of the drivers being maintained open by pressure from the plungers 320 until the driver heads 85 have reached a position where the head of 90 the staple upon the adjacent presenter block is within the open catch. Just at this time pressure from the plungers 320 on the catches 312 is relieved by their stop nuts 321 coming in contact with the supports on 95 which the plungers are mounted, and the catches are allowed to close tightly upon the heads of the staples through the action of their springs 314. Continued downward movement of the gripper carriages acts to 100 retract the presenter blocks within their guides 330 through engagement of the forked arms 376 with the pins 378, and as the drivers 300 continue to move downwardly with the gripper carriages the 105 staples held by the driver heads are carried with them. During this movement the sleeves 302 carrying the drivers are turned about their pivots by the springs 318 until the driver heads and the staples carried 110 thereby contact with the upper surfaces of their adjacent upper gripper jaws. The action of the cam groove 162 continues until the gripper carriages reach a point at the bottoms of their curved guides where the 115 stretched upper has been brought around the curved surface on the top of the last and lies in a plane at substantially right angles to the bottom of the last. When the grippers have reached this position, the outer 120 ends of the links 72 which have previously engaged the beveled surfaces of the blocks 240 on the spring supported arms 236 and 251, have depressed said arms in this movement and placed themselves within the recesses 242 formed by the hooked ends of the arms and the beveled blocks.

A dwell now occurs in the cam groove 162, and at this time the cam groove 210 immediately begins to operate upon its 130

roll 212 forming a continuous automatic movement for the grippers. Movement of the roll 212 acts to turn the bell crank lever 214 about its pivot, and through the mechanism heretofore described moves the curved guide 12 carrying the toe gripper supports 92 and the side gripper supports 58, inwardly simultaneously to place the margin of the upper within the last edge. During this movement inwardly of the grippers the short links 78, which connect each of the links 72 with its lever 76, are resting in the sockets 242 of the arms 236 and 251 and as these arms remain stationary while the links 72 and levers 76 move inwardly, the connecting links 78 are turned about their connections with the levers 76 to a position where the straining of the upper upwardly is enabled to draw the grippers with it relatively to their supporting carriages, the movement of the toe grippers taking place in the slots 96 and of the side grippers in the slots 64. This upward motion of the grippers continues as long as the inward movement of the grippers continues, so that when the hammers 274 are tripped as heretofore explained, at the end of the inward movement the upper has been placed close to the insole and is in proper position to be secured thereto. As heretofore explained, however, the toe grippers should at this time be given a further movement to bring them in parallelism with the edge of the last, in order that the upper may be placed smoothly upon the last and snugly about its edge. This is accomplished through the further motion of the cam groove 210 compressing the spring 266 carried within the socketed block 260 at the rear of the machine, thus spreading the toggle links 256 and moving the toe gripper supports outwardly in the curved guideway 12. In operating upon a right last, as illustrated in the drawings, owing to the curvature of the side of the last the toe gripper support at the right hand side of the center line of the machine will come to rest by engagement with its stop 272 in the guide 12 before the other toe gripper support will engage its stop. After the first stop has been engaged, however, further pressure of the spring 266 will force socketed block 260 bodily to the left, it being sustained in this movement by the table 7, the toggle links 256 pivoting upon their pins 252 on the toe supports and pin 258 on the socketed block until the left hand toe gripper support has moved sufficiently to the left in the curved guide 12 to engage its stop 272. One of the push rods 104 is engaged by the block 260 in its movement but moves with the block owing to its swiveled connection on one of the studs 396. This movement of the socketed block bodily to the left is permitted by the universally

connected link 268 between the bell crank lever 214 and the socketed block. If a left last is being operated upon, the action would be the same as just described, with the exception that the toe gripper support at the left of the center line of the machine will meet its stop 272 before the right hand toe gripper support, and consequently the socketed block 260 will be moved to the right bodily instead of to the left.

After the movement just described the upper at the toe is in proper position to receive the staples to secure it to the insole. The driving of the staples at the toe of the shoe is accomplished by the tripping of the latches 286 by engagement with the stops 272 when the turning movement of the toe grippers is completed, thus freeing the hammers 274, so that they may be forced upwardly under the expansion of the springs 278, this movement of the hammers 274 forcing the drivers 300 through their sleeves 302 and driving the staples through the upper and the insole, the staples being guided in their movement by contact with the upper surfaces of the grippers on which they rest. The hammers 274 at the sides of the shoe are actuated to drive the staples in a similar manner to that just described for the toe of the shoe by their latches 286 engaging pins 287, carried by the side gripper supporting blocks 56, at the completion of the inner movement of the supports 58, which occurs at about the time the toe hammer latches are tripped.

The cam 162 comes into operation again immediately after the staples are driven, while at this time the cam groove 210 is provided with a dwell. The action of the cam groove 162 at this time upon its roll 164 operates to force the arm 166 upwardly, carrying with it the rod 172 and the side and toe gripper actuating rods 176 and 178. As heretofore explained, the first portion of the movement of these rods does not actuate the gripper carriages as the pins 184 on said carriages slide in the slots 180 in the actuating rods, but this movement operates to allow sufficient engagement between the actuating rods and the levers 290 for retracting the hammers 274 a sufficient distance to allow the latches 286 to be moved by their springs into engagement with the surfaces 275 of said hammers, thus holding them, with the springs 278 compressed, in position to deliver another blow upon the drivers 300 on the next cycle of operations. Retractions of the hammers 274 allows the springs 306 to expand and this expansion opens the catches 312 by which the drivers are held on the staples and snaps the driver heads off of the staples. As hereinbefore explained, during the retraction of the driver hammers the bosses 181 on the ends

of the actuating rods engage, and move the tail pieces 380 secured to the pins 80 carrying the pawls 82, and the hold of the grippers upon the upper is thus loosened. The pulled over shoe is preferably removed from the machine at this time as it is now clear of all mechanism which previously held it in position. Further movement of the tail pieces 380 force the pins 74 on the links 72 along the slots in the legs of the grippers, thus opening the grippers. This movement of the links 72 also withdraws their outer ends from the recesses 242 of the arms 236 and 251. The moving parts having thus been freed from the shoe and from the surrounding mechanism all the gripper carriages may be moved outwardly and then upwardly to their initial position, carrying the grippers and drivers with them. This is accomplished by engagement of the bottoms of the slots 180 of the actuating rods with the pins 184 on the gripper carriages, the cam 210 first forcing the gripper supports outwardly and then the cam 162 forcing the gripper carriage upwardly until the grippers again rest slightly above the plane of the bottom of the last with their jaws open and with the drivers 300 in a plane substantially parallel with the plane of the presenter blocks 332, which have again been brought forwardly in their guides 330 by engagement of the arms 376, on their upward movement, with the pins 378 as heretofore explained. Another shoe of the same size may be pulled over without altering any of the adjustments, but if the size or width is changed corresponding adjustments are made by movements of the proper levers. From the foregoing it will be seen that the pulling over operation is much simplified over prior machine pulling over, for obviously, the skill required for operating a machine of the type herein described is very much less than where the judgment of the operative must be constantly used to determine the "set" of the stretched upper upon the last, for the reason that the scales and adjustment provided for the controlling levers allow the machine to be adjusted mechanically to properly position a last of any given curvature or formation beneath its upper, and thus insure a proper alinement of the tip line upon the last when the upper is thereafter placed thereabout without further adjustment or manipulation of any sort by the operative.

The term "positioning device" used in some of the following claims is not to be understood as limiting such claims to a device for preliminarily positioning the last upon its support, but such expression is intended to cover broadly any device used to aid in any way the positioning of the upper upon the last. Also, the phrase "top side of the plane of the bottom of the last" used in some of the following claims is intended to designate that side of the last bottom on which the body of the last is situated, whether or not the last be supported sole down.

Of course it will be understood that the number of grippers employed, and the spacing and arrangement of the same, may be varied at will, and while I have found the arrangement herein illustrated to furnish excellent results, my invention, nevertheless, is not restricted thereto and furthermore, nothing herein contained is to be construed as limiting my invention in scope to the particular embodiment of the invention selected for illustration and explanation. On the contrary the specific machine illustrated may be variously altered and modified both in structure and operation and still fall within the spirit and scope of my invention. Such alteration and modification will be apparent to those skilled in the art.

Having described my invention by means of one embodiment thereof as an illustration of the same, what I claim in addition thereto and desire to secure by Letters Patent, is,—

1. A pulling over machine comprising means for supporting a shoe, sole downward, pulling over means constructed and arranged to be movable about the last, and means for inserting a fastener into the pulled over shoe while so supported.
2. A pulling over machine comprising means for supporting a last, sole downward, means for pulling an upper over the last, and automatic means for inserting a fastener through the upper and into the insole while so supported.
3. A pulling over machine comprising means for supporting a last, sole downward, a single means for stretching and placing an upper about said last with its margin within the last edge, and means for securing said over placed upper to the insole while so supported.
4. A pulling over machine comprising means for supporting a last, sole downward, a single means for stretching and placing an upper about said last with its margin within the last edge, and means for securing said over placed upper to the insole at a plurality of separate points simultaneously while so supported.
5. A pulling over machine comprising means for supporting a shoe, sole downward, pulling over means, and automatic means for inserting a fastener upwardly into the bottom portion of the pulled over shoe while so supported.
6. A pulling over machine comprising means for supporting a shoe, sole downward, pulling over means, and means for inserting a fastener upwardly into the tread

face of the insole while so supported and obliquely with relation to said face.

7. A pulling over machine comprising means for supporting a shoe, sole downward, pulling over means, means for placing a fastener in driving position beneath the shoe, and means for thereafter forcing said fastener upwardly into the pulled over shoe.

8. A pulling over machine comprising 10 means for supporting a shoe, sole downward, pulling over means, a device for holding a fastener, means for moving said device to place said fastener in driving position beneath the shoe, and means for thereafter actuating said device to force said fastener upwardly into the pulled over shoe.

9. A pulling over machine comprising 15 means for supporting a shoe, sole downward, pulling over means, a source of fastener supply, means for conveying a fastener from said source of supply into driving position beneath the pulled over shoe, and means for presenting fasteners to said conveying means.

10. A pulling over machine comprising 20 means for supporting a shoe, sole downward, pulling over means, a source of fastener supply, means for conveying a fastener from said source of supply into driving position beneath the pulled over shoe, and means controlled by the movement of said conveying means for presenting fasteners thereto.

11. A pulling over machine comprising 25 means for supporting a shoe, sole downward, pulling over means, a source of fastener supply, means for selecting fasteners from said source of supply, and means for engaging a selected fastener and conveying 30 it into driving position beneath the pulled over shoe.

12. A pulling over machine comprising 35 means for supporting a shoe, sole downward, pulling over means, a source of fastener supply, means for selecting fasteners from said source of supply, and means for engaging a selected fastener and conveying 40 it into driving position beneath the pulled over shoe, the action of said conveying means being controlled by the pulling over means.

13. A pulling over machine comprising 45 means for supporting a shoe, sole downward, pulling over means, a source of fastener supply, means for selecting fasteners from said source of supply one at a time, and means for engaging said selected fastener and conveying it into driving position 50 beneath the pulled over shoe, the action of both said selecting and conveying means being controlled by the pulling over means.

14. A pulling over machine comprising 55 means for supporting a shoe, sole downward, grippers for seizing the upper, means 60 for moving said grippers inwardly beneath

the shoe to place the edge of the upper adjacent the sole of the shoe, and means for inserting a fastener through the upper and into the shoe while so supported.

15. A pulling over machine comprising 70 means for supporting a last, sole downward, means for pulling an upper over said last, and means for inserting a plurality of fasteners through the upper and into the insole, while so supported, each substantially 75 the same distance from the edge of the last, said distance being determined by the pulling over means.

16. In a pulling over machine comprising 80 means for supporting a last, sole downward, grippers for seizing and pulling an upper over said last, and means for inserting a fastener adjacent said grippers through the upper and into the insole, while so supported, said grippers being constructed and arranged 85 to form a guide to direct said fastener in its movement.

17. In a pulling over machine, the combination of means for supporting a last, sole 90 downward, means for seizing and pulling over the upper constructed and arranged to be movable about the last, and means for securing said pulled over upper to the shoe while supported in said position and before the hold of the pulling over means is released.

18. In a pulling over machine the combination of means for supporting a shoe, sole 100 downward, pulling over means constructed and arranged to be movable across the edge of the last, and means for inserting a multi-pointed fastener into the pulled over shoe while so supported.

19. In a pulling over machine the combination of means for supporting a last, sole 105 downward, grippers for seizing the edge of an upper on said last and actuating devices therefor, a source of fastener supply, a fastener holder, means for presenting a fastener to the holder from the source of supply, and means for actuating said holder to insert the fastener through the upper and into the last while so supported.

20. A pulling over machine comprising 110 last supporting means for supporting a shoe sole downward, pulling over means arranged thereabout and adapted to seize the margin of an upper extending loosely in assembled position over the top of the forepart of the last, fastener inserting devices, and mechanism operating to move said pulling over means from a position above to a position below the plane of the bottom of the last and to actuate the inserting devices to insert a fastener through the pulled over upper into the sole.

21. A pulling over machine, comprising 115 means for supporting a last, sole downward, pulling over means arranged thereabout, and adapted to seize the edge of the upper, and 120

- mechanism to move said pulling over means downward to place the upper about the last, inward to place the edge of the upper within the last edge and upward to place the edge of the upper adjacent the sole. 5
22. A pulling over machine, comprising means for supporting a last, sole downward, pulling over means arranged thereabout, extending substantially parallel to the plane 10 of the last sole and adapted to seize the edge of the upper, mechanism to move said pulling over means downward to place the upper about the last, inward to place the edge of the upper within the last edge, and 15 upward to place the edge of the upper against the sole, and means for securing the pulled over upper to the sole. 20
23. In a pulling over machine, pulling over means comprising two pairs of toe gripper jaws adjacent each other on opposite sides of the center of the tip of the toe and extending obliquely to the sole edge of the last, and means to move said grippers in to a position with their forward edges 25 substantially parallel to said last sole edge. 24. In a pulling over machine, pulling over means comprising two pairs of toe gripper jaws adjacent each other on opposite sides of the center of the tip of the toe 30 and extending obliquely to the sole edge of the last, and means to move said grippers into a position with their forward edges substantially parallel to said last sole edge, said jaws being formed to corrugate the 35 margin of the upper at the toe portion thereof. 25. In a pulling over machine, toe pulling over means comprising two pairs of gripper jaws, having their engaging faces provided 40 with transverse corrugations extending between their side edges, lying on opposite sides of the center of the tip of the toe and spaced apart substantially the width of one of the corrugations. 45
26. In a pulling over machine, a plurality of toe pulling over means movable about the last and arranged on each side of the center of the tip of the toe, said means being constructed to shape to the curvature of the toe, where held by said pulling over means, the 50 entire marginal portion of the upper, operating means therefor, and means for securing said shaped upper in pulled over position. 55
27. In a pulling over machine, a plurality of toe pulling over means movable about the last and arranged on each side of the center of the tip of the toe, said means being constructed to shape to the curvature of the toe, where held by said pulling over means, the 60 entire marginal portion of the upper, operating means therefor, and means for securing said shaped upper in pulled over position. 65
28. In a pulling over machine, pulling over means including two pairs of gripper jaws movable about the last and arranged 70 one on each side of the center of the tip of the toe, means for causing said jaws to seize the marginal portion of the upper, said jaws being constructed to shape to the curvature of the toe the entire marginal portion of the upper from the outer edge of one pair of jaws to the outer edge of the other pair of jaws, and operating means therefor. 75
29. In a pulling over machine, pulling over means composed of four pairs of gripper jaws, a pair on each side of the shoe for transverse pulling and two pairs closely adjacent each other at the tip of the toe of the shoe for direct longitudinal pulling from each pair. 80
30. In a pulling over machine, pulling over means comprising a plurality of pairs of gripper jaws arranged about the sides and toe of the shoe with their gripping surfaces lying in substantially the same plane prior to the pulling over operation. 85
31. In a pulling over machine, pulling over means comprising a plurality of pairs of gripper jaws arranged about the sides and toe of the shoe with their gripping surfaces in a plane substantially parallel to the plane of the bottom of the shoe prior to the pulling over operation. 90
32. A pulling over machine comprising last supporting means, grippers movable to pull an upper over the last arranged with their gripping surfaces in substantially the same plane, means for causing said grippers to seize the edge of the upper, and provision for stretching and positioning the upper 95 prior to the completion of the over-placing operation. 100
33. A pulling over machine comprising last supporting means, grippers, means to actuate the same to pull an upper over the last and provision for causing said grippers to seize the edge of and stretch the upper in advance of the over-placing movement. 105
34. A pulling over machine comprising last supporting means, grippers movable to pull an upper over the last arranged with their gripping surfaces in substantially the same plane, means for causing said grippers to seize the edge of the upper, and means under control of the operative for stretching and positioning the upper prior 110 to the completion of the over-placing operation. 115
35. A pulling over machine comprising a last support, means located at the top side of the plane of the bottom of the last to engage the upper above the plane of the bottom of the last and stretch the same, and provision for moving said means to thereafter carry the margin of the upper about the edge of 120 the last. 125
36. A pulling over machine comprising a last support for sustaining a last sole downward, and means located at the top side of the plane of the bottom of the last to engage 130

and stretch the upper and thereafter carry the margin thereof about the edge of the last.

37. A pulling over machine comprising a last support, means located at the top side of the plane of the bottom of the last for engaging and stretching the upper both longitudinally and transversely and thereafter carrying the margin thereof about the edge of the last, and provision for securing the upper in the pulled over position.

38. A pulling over machine comprising last supporting means, grippers adapted to seize the margin of the upper located at the top side of the plane of the bottom of the last, means to actuate said grippers to carry the margin of the upper downward and place the upper about the curved portion of the last, and provisions for positioning the upper longitudinally prior to the completion of the over-placing movement.

39. In a pulling over machine comprising last supporting means, grippers adapted to seize the margin of the upper located at the top side of the plane of the bottom of the last, means to actuate said grippers to carry the margin of the upper downward and place the upper about the curved portion of the last, and provisions for stretching the upper transversely prior to the completion of the overplacing movement.

40. A pulling over machine comprising last supporting means, pulling over means constructed and arranged to engage the toe portion of an upper on the last while extending in substantially a single plane, and means for stretching and positioning the upper while in this position and thereafter carrying it about the last.

41. A pulling over machine comprising last supporting means, gripping means arranged at the sides and toe of the last, means for causing said gripping means to seize the upper, means for moving the last with relation to the toe gripping means to stretch the upper longitudinally, and means for moving the side gripping means with relation to the last stretch the upper transversely.

42. A pulling over machine comprising last supporting means, gripping means arranged at the sides and toe of the last, means for causing said gripping means to seize the upper, means for moving the last with relation to the toe gripping means to stretch the upper longitudinally, and means for moving the side gripping means with relation to the last to stretch the upper transversely, both of said last named means being under control of the operative.

43. A pulling over machine comprising last supporting means, means for gripping the sides and toe of the forepart of an upper on the last while extending in substantially

a single plane, and means for changing the relative positions of the last and gripping means for stretching and positioning the upper and thereafter carrying it about the last.

44. A pulling over machine comprising last supporting means, means for gripping the toe portion of an upper on the last while extending in substantially a single plane, and means for changing the relative positions of the last and gripping means for stretching and positioning the upper while in this position both longitudinally and transversely and thereafter carrying it about the last.

45. A pulling over machine comprising last supporting means, pulling over means for engaging the upper, means for changing the relative positions of the last and pulling over means to stretch and position the upper, and means for thereafter moving said pulling over means in a direction to place said stretched upper about the curved portion of the forepart of the last.

46. A pulling over machine comprising a plurality of pairs of gripper jaws arranged at the toe thereof, means for causing said jaws to seize the edge of the upper, means for moving said pairs of jaws to place the edge of the upper within the edge of the last, and thereafter moving them to bring their edges in parallelism with the edge of the last.

47. A pulling over machine comprising a plurality of pairs of gripper jaws arranged about the last on opposite sides and at the toe thereof, said jaws having their edges normally in parallelism with the edge of the last, means for causing all of said jaws to seize the edge of the upper, means for moving all of said pairs of jaws to place the edge of the upper within the edge of the last, and means for thereafter moving said toe jaws to bring their edges in parallelism with the edge of the last.

48. A pulling over machine comprising last supporting means, curved guideways about said supporting means vertically arranged with respect to the plane of the last sole, grippers sustained in said guideways for seizing the upper and means for moving said grippers in their guideways in a direction to place the upper about the last.

49. A pulling over machine comprising pulling over means for seizing the loose upper, provision for moving said means to place the upper about the curved portion of the forepart of the last, and provision for thereafter moving said means inwardly beyond the last edge and in a direction toward the bottom of the last.

50. A pulling over machine comprising pulling over means for seizing the loose upper, mechanism for moving said means

to place the upper about the curved portion of the toe of the last, and mechanism for thereafter moving said means inwardly beyond the last edge and in a direction toward the bottom of the last, the movement toward the last being controlled by the inward movement.

51. A pulling over machine comprising shoe supporting means, a plurality of grippers arranged thereabout and extending with their gripping surfaces in a plane substantially parallel to the shoe sole, and means for maintaining the inner edges of said grippers substantially the same distance from the shoe edge whatever the size of shoe being operated upon.

52. In a pulling over machine, side and toe pulling over devices, and means for preliminary shifting said pulling over devices for rights and lefts.

53. In a pulling over machine, pulling over means at the end of the toe constructed and arranged to be shifted bodily transversely of the machine for rights and lefts.

54. In a pulling over machine, pulling over means at the end of the toe, comprising two pairs of gripper jaws constructed and arranged to be shifted bodily transversely of the machine for rights and lefts.

55. In a pulling over machine, toe pulling over means, a transversely movable slide sustaining said means, and means for moving said slide comprising a lever pivoted on the machine frame having one arm connected to said slide and a controlling lever connected to the other arm thereof.

56. In a pulling over machine, toe pulling over means, a transversely movable slide sustaining said means, and means for moving said slide comprising a lever pivoted on the machine frame having one arm connected to said slide and a controlling lever connected to the other arm thereof, one of said connections being adjustable.

57. In a pulling over machine, toe pulling over means, a transversely movable slide sustaining said means, means for moving said slide comprising a lever pivoted on the machine frame having one arm connected to said slide and a controlling lever connected to the other arm thereof, and means for locking said slide in any desired position.

58. In a pulling over machine, pulling over means, and provisions for maintaining the same in uniform work receiving relation with the edge of the last whatever the size or style of shoe being operated upon.

59. In a pulling over machine, pulling over means, comprising gripper jaws and provisions for maintaining the inner edges thereof in parallelism with the edge of the last when in work receiving position whatever the size or style of shoe being operated upon.

60. In a pulling over machine, pulling over means on each side of the last, devices for maintaining the same in angular relation to the center line of the machine, said devices being constructed and arranged to cause the angles at each side to be equal or unequal, and a controller for said devices.

61. In a pulling over machine, pulling over means on each side of the shoe, movable supports for said means, a lever pivoted adjacent each support, a yoke connecting said levers, means for maintaining said supports and levers in engagement, and means for shifting said yoke whereby said supports are moved.

62. In a pulling over machine, pulling over means on each side of the shoe, pivotally mounted supports for said means, a bell crank lever pivoted adjacent each support and equidistant from the machine center line with their angles pointing in opposite directions, a yoke connecting said levers, means for maintaining said supports and levers in engagement, and means for shifting said yoke transversely whereby said supports are moved about their fulcrums.

63. In a pulling over machine, pulling over means, a pivotally mounted support therefor, a stop, means for maintaining said support and stop in engagement, and means for changing the relation between said stop and the fulcrum of said support during said engagement.

64. In a pulling over machine, pulling over means, a pivotally mounted support therefor, a stop, yielding means for maintaining said support and stop in engagement, and means for changing the relation between said stop and the fulcrum of said support during said engagement.

65. In a pulling over machine, a pair of gripper jaws, a fulcrumed support therefor, and automatic means to move said support about its fulcrum to bring the inner edges of said jaws in parallelism with the last edge.

66. In a pulling over machine, toe and side pulling over means, a movable support for the latter, and means for changing the location of the toe pulling over means with relation to the center line of the machine and simultaneously changing the angular relation thereof to the side pulling over means.

67. In a pulling over machine, toe and side pulling over means, mechanism for shifting the toe pulling over means transversely of the machine, and movable devices engaging the side pulling over means controlled by said mechanism for causing a change in the location of said side pulling over means.

68. In a pulling over machine, side pulling over means mounted for angular and

transverse movement with relation to the machine center line, provision for moving said means transversely, and means for simultaneously causing them to move angularly.

5 79. In a pulling over machine, side pulling over means mounted for angular and transverse movement with relation to the machine center line, mechanism for moving 10 said means transversely, and means controlled by said mechanism for simultaneously causing them to move angularly.

70 80. In a pulling over machine, pulling over means, mechanism for adjusting said means transversely of the machine and mechanism for automatically adjusting said means angularly with relation to the center line.

15 81. In a pulling over machine, pulling over means, mechanism for adjusting said means transversely of the machine, and mechanism for automatically adjusting said means angularly with relation to the center line, the latter adjustment being controlled by the former.

20 82. In a pulling over machine, side pulling over means mounted for movement transversely of the machine, operating mechanism therefor comprising a lever 30 pivoted on the frame, a connection between one end of said lever and the means on one side and between the other end of said lever and the means on the other side, and means for turning said lever about its pivot for 35 actuating said connections to move the pulling over means.

83. In a pulling over machine, side pulling over means mounted for movement transversely of the machine, operating mechanism 40 therefor comprising a lever pivoted on the frame, a connection between one end of said lever and the means on one side, and between the other end of said lever and the means on the other side, means for turning said 45 lever about its pivot for actuating said connections to move the pulling over means, and locking devices for said lever.

84. In a pulling over machine, pulling over means mounted for movement transversely of the machine, adjusting mechanism 50 for said means, means for initially actuating said mechanism to move the pulling over means and separate means for increasing said movement.

55 85. In a pulling over machine, side pulling over means mounted for movement transversely of the machine, operating mechanism therefor including a lever pivoted on the frame, a connection between one end of 60 said lever and the means on one side, and between the other end of said lever and the means on the other side, manually controllable means for initially turning said lever about its pivot to move the pulling over

means and automatic means for increasing 65 said movement.

76. In a pulling over machine, pulling over means and provisions for adjusting said means longitudinally and transversely of the machine simultaneously.

70 77. In a pulling over machine, pulling over means, mechanism for adjusting said means longitudinally of the machine, and mechanism for automatically adjusting said means transversely of the machine.

75 78. In a pulling over machine, pulling over means, mechanism for adjusting said means longitudinally of the machine, and mechanism for automatically adjusting said means transversely of the machine, the latter 80 adjustment being controlled by the former.

85 79. In a pulling over machine, pulling over means, mechanism for adjusting said means longitudinally of the machine, mechanism controlled by said first named mechanism for causing said pulling over means to be adjusted transversely of the machine and means for operating said last named mechanism independently of said first named mechanism.

90 80. In a pulling over machine, pulling over means, mechanism for adjusting said means longitudinally of the machine, devices for adjusting said means transversely of the machine, and operative connections 95 between said mechanism and devices, whereby a movement of one communicates movement to the other.

95 81. In a pulling over machine, pulling over means, mechanism for adjusting said means longitudinally of the machine, devices for adjusting said means transversely of the machine, and means for operating said devices independently of said mechanism.

100 82. In a pulling over machine, pulling over means, a frame sustaining said means and mounted for longitudinal adjustment, mechanism carried by said frame for adjusting said means transversely and comprising a lever, a connection between said lever and pulling over means, a crank or said lever, and a link from said crank to a stationary part of the machine, whereby a movement of said frame longitudinally will 110 actuate said crank to turn said lever and adjust the pulling over means transversely.

115 83. In a pulling over machine, pulling over means, a frame sustaining said means and mounted for longitudinal adjustment, mechanism carried by said frame for adjusting said means transversely and comprising a lever, a connection between said lever and pulling over means, a crank on said lever, a link from said crank to a stationary part of the machine, whereby a 120 movement of said frame longitudinally will actuate said crank to turn said lever and adjust the pulling over means transversely,

- and means for turning said lever independently of said crank.
84. In a pulling over machine, pulling over means, and provisions for adjusting said means longitudinally and transversely of the machine and angularly with relation to the center line.
85. In a pulling over machine, pulling over means, mechanism for adjusting said means longitudinally and transversely of the machine and angularly with relation to the center line, and a single controller for said mechanisms.
86. In a pulling over machine, pulling over means, provision for adjusting said means longitudinally of the machine, and provision for automatically adjusting said means transversely of the machine and angularly with relation to the machine center line.
87. In a pulling over machine, pulling over means, mechanism for adjusting said means longitudinally of the machine, mechanism for automatically adjusting said means transversely of the machine, and mechanism for automatically adjusting said means angularly with relation to the center line, the last adjustment being controlled by the transverse adjustment.
88. In a pulling over machine, pulling over means, a support for the shoe, and provisions for adjusting said pulling over means and support longitudinally of the machine simultaneously.
89. In a pulling over machine, pulling over means, a support for the shoe, and provision under control of the operative for adjusting said pulling over means and support longitudinally of the machine simultaneously.
90. In a pulling over machine, pulling over means, a support for the shoe, and mechanisms operating simultaneously for adjusting said pulling over means and support longitudinally and said support vertically of the machine.
91. In a pulling over machine, pulling over means, a support for the shoe, and provision for adjusting said pulling over means and support longitudinally and said support vertically of the machine and a single controller therefor.
92. In a pulling over machine, pulling over means, a support for the shoe, and mechanisms operating simultaneously for adjusting said pulling over means longitudinally, transversely and angularly of the center line, and the support longitudinally and vertically of the machine.
93. In a pulling over machine, pulling over means, a shoe support, mechanisms for adjusting said means and support longitudinally of the machine, and mechanisms for automatically adjusting said means transversely of the machine and angularly with relation to the center line and said support vertically of the machine.
94. In a pulling over machine, pulling over means, a shoe support, mechanism for adjusting said support longitudinally of the machine, mechanism controlled by said first named mechanism for adjusting said pulling over means longitudinally of the machine, and means for adjusting said pulling over means independently of said first named mechanism.
95. In a pulling over machine, pulling over means, a shoe support, mechanism for adjusting said support longitudinally of the machine, mechanism controlled by said first named mechanism for adjusting said pulling over means longitudinally of the machine, and manually controllable means for adjusting said pulling over means independently of said first named mechanism.
96. In a pulling over machine, pulling over means, a longitudinally movable frame sustaining said means and having a longitudinally arranged slot, operating means for said frame comprising a block provided with a slot angularly arranged with relation to the slot in the frame and mounted for transverse movement in said frame, a fixed pin engaging both slots, and means for actuating the block with relation to the frame.
97. In a pulling over machine, pulling over means, a longitudinally movable frame sustaining said means and having a longitudinally arranged slot, operating means for said frame comprising a block provided with a slot angularly arranged with relation to the slot in the frame and mounted for transverse movement in said frame, a fixed pin engaging both slots, means for actuating the block with relation to the frame, and means for locking said actuating means at any desired position of the frame.
98. In a pulling over machine, a positioning device for engaging the last and extending above its tread face, means for placing an upper about the last, and means for withdrawing such device from engagement with the last before the completion of the overplacing operation.
99. In a pulling over machine, a positioning device for engaging the last, means for placing an upper about the last, and means controlled by the overplacing means, for withdrawing said device from engagement with the last before the completion of the overplacing operation.
100. In a pulling over machine, a positioning device for engaging the edge of the last, pulling over means disposed with relation to said device to place an upper about a last positioned by said device, said device being mounted for withdrawal from and within the edge of the last, and means for effecting such withdrawal.

101. In a pulling over machine, a yieldingly mounted positioning device for engaging the edge of the last, pulling over means disposed about the positioning device to place an upper about a last positioned by said device, said device being mounted for withdrawal from and within the edge of the last, and means for effecting such withdrawal during the action of the pulling over means. 65
102. In a pulling over machine, grippers for seizing and pulling over the upper, a support for said grippers, mechanism for moving said support to place the grippers within the last edge, and a positioning device for engaging the edge of the last mounted on said support. 70
103. In a pulling over machine, a yieldingly mounted positioning device for engaging the edge of the last, means for placing an upper about the last, and a tail-piece for said device projecting into the path of movement of the overplacing means. 80
104. In a pulling over machine, means for gripping and placing an upper about a last, shoe supporting means for supporting the last for the action of the pulling over means, a stop arranged to engage the edge of the last at the toe, means for moving said stop in a direction to force the last heelward with relation to the pulling over means, and means for thereafter withdrawing said stop from engagement with the last edge. 90
105. In a pulling over machine, pulling over means for placing an upper about a last, shoe supporting means for supporting the last for the action of the pulling over means, a stop arranged to engage the edge of the last at the toe, means under control of the operative for moving said stop in a direction to force the last heelward with relation to the pulling over means, and automatic means for thereafter withdrawing said stop from engagement with the last edge. 95
106. In a pulling over machine, the combination with last supporting means and means for placing an upper about the last, of a toe positioning device for the last sustained by said supporting means, and means for moving said device and the last relative to the last support. 100
107. In a pulling over machine, the combination with last supporting means and means for placing an upper about the last, of a toe positioning device, and means for moving said device and the last relative to the last support and for removing said device from the last. 110
108. In a pulling over machine, a positioning device for engaging the last, pulling over means disposed about the last positioned by said device, means for initially moving said device in one direction with respect to the pulling over means, and means for thereafter continuing said movement. 115
109. In a pulling over machine, a positioning device for engaging the last, pulling over means disposed about the last positioned by said device, means under control of the operative for initially moving said device in one direction, and automatic means for thereafter continuing said movement. 120
110. In a pulling over machine, a positioning device for engaging the last, pulling over means disposed about the last positioned by said device, means for initially moving said device in one direction, including a spring arranged to be compressed during said movement, and means for thereafter releasing said spring for continuing said movement. 125
111. In a pulling over machine, a positioning device for engaging the last, pulling over means disposed about the last positioned by said device, means for initially moving said device in one direction, and means for thereafter continuing said movement a predetermined distance. 90
112. In a pulling over machine, a positioning device for engaging the last normally in last receiving position, pulling over means disposed about the last positioned by said device, means for withdrawing said device from engagement with the last, means for returning said device into last receiving position upon release of said withdrawing means, and means for actuating the pulling over means to carry the upper about the last. 95
113. In a pulling over machine, a transversely arranged guideway, pulling over means on each side of the tip of the toe movably mounted in said guideway, provision for moving said means in opposite directions, and devices for limiting the amount of such movement. 105
114. In a pulling over machine, a transversely arranged guideway, pulling over means on each side of the tip of the toe movably mounted in said guideway, provision for moving said means in opposite directions, and adjustable devices for limiting the amount of such movement. 110
115. In a pulling over machine, a transversely arranged guideway, pulling over means on each side of the tip of the toe movably mounted in said guideway, provision for moving said means in opposite directions, devices for limiting the amount of said movement, and means for adjusting said devices at equal or unequal distances from the initial position of the pulling over means. 115
116. In a pulling over machine, toe pulling over means, a transversely arranged guideway sustaining said means, a stop for 120
- 125

said pulling over means, a slide, connections between said stop and slide, and means for moving said slide and thereby changing the position of the stop.

5 117. In a pulling over machine, toe pulling over means, a transversely arranged guideway sustaining said means, stops for said means, a slide connected to said stops, and means for moving said slide comprising 10 a lever connected to said slide, and an actuator for said lever.

118. In a pulling over machine toe pulling over means, a transversely arranged guideway sustaining said means, stops for 15 said means, a slide connected to said stops, and means for moving said slide comprising a lever connected to said slide and an actuator connected to said lever, one of said connections being adjustable.

20 119. In a pulling over machine, toe pulling over means, comprising two pairs of gripper jaws, supports for said jaws, provision for moving said supports transversely in one direction collectively, and for 25 moving said supports transversely independently.

120. In a pulling over machine, toe pulling over means, comprising two pairs of gripper jaws, supports for said jaws, mechanism for moving said supports transversely 30 in one direction collectively, mechanism for moving said supports transversely each in an opposite direction, devices for limiting the latter movement of said supports, and 35 means for adjusting said devices with relation to the initial position of said supports.

121. In a pulling over machine, toe pulling over means, comprising two pairs of gripper jaws, supports for said jaws, mechanism 40 for moving said supports transversely in one direction collectively, mechanism for moving said supports transversely each in an opposite direction, devices for limiting the latter movement of said supports, and 45 means controlled by said first named mechanism for adjusting said devices with relation to the initial position of said supports.

122. In a pulling over machine, last supporting means, pulling over means disposed 50 about a last on said supporting means, provision for moving said last supporting means into position to receive different sized lasts, means for guiding said supporting means in its movement in a direction at an 55 angle to the machine center line, and actuating devices for the pulling over means to carry the upper about the last sustained by the last supporting means.

123. In a pulling over machine, a heel 60 support, pulling over means disposed about a last sustained on said support, provision for moving said support into position relative to the pulling over means to receive different sized lasts, means for guiding said

support in its movement in the direction of 65 the swing of the last, and actuating devices for the pulling over means to carry the upper about the last.

124. In a pulling over machine, a heel support, pulling over means, mechanism for 70 moving said support into position to receive different sized lasts, means for guiding said support in its movement in the direction of the swing of the last, mechanism for adjusting said guiding means into position for 75 rights and lefts, and actuating devices to cause the pulling over means to carry the upper about a last positioned by said support.

125. In a pulling over machine, pulling 80 over means, a heel support, a toe positioning device, means for simultaneously moving said heel support and toe positioning device to one side or the other with relation to the pulling over means for positioning 85 rights and lefts with relation to the pulling over means, and actuating mechanism to cause the pulling over means to carry an upper about the last positioned by said support and device. 90

126. A pulling over machine comprising pulling over means, devices for causing said pulling over means to seize the upper, provision for moving said pulling over means to pull over the upper, and provision for removing said devices from the path of movement of the pulling over means. 95

127. A pulling over machine comprising a movable carriage, a pair of gripper jaws and means for closing them mounted on said carriage, a push rod for engaging said closing means to close the jaws, means for moving said carriage in a direction to pull over the upper, and means for removing said push rod from its path of movement. 100

128. In a pulling over machine, pulling over means, a slide sustaining said means, a cam-ended lever pivoted on the frame having one end connected to said slide, and means for engaging the cam-end of said 110 lever to actuate the slide.

129. A pulling over machine comprising means for supporting a last, sole downward, grippers for seizing the edge of the upper, automatic means for moving said grippers 115 while holding the upper from a position below the last edge to a position within the last edge and for causing said grippers to move upwardly as they move inwardly.

130. A pulling over machine comprising 120 means for supporting a last, sole downward, grippers for seizing the edge of the upper, a link engaging said grippers, an actuating lever for said link, means for moving said grippers while holding the upper from a position below the last edge to a position within the last edge, a short link between said first named link and its actuating lever, and 125

- means for holding one end of said short link from inward movement with the grippers, whereby the short link acts as a crank and allows upward movement of the grippers during their inward movement.
131. In a pulling over machine, a tip measurer, means to move said measurer longitudinally of the shoe, and means to actuate the same toward and from the shoe during such movement.
132. In a pulling over machine, a tip measurer movable longitudinally with relation to the shoe, means to move said measurer vertically with relation to the shoe during its longitudinal movement, and means to move said measurer longitudinally independent of vertical movement.
133. In a pulling over machine, pulling over means, a tip measurer, means to move said pulling over means longitudinally of the shoe for varying lengths of tip, and means for simultaneously moving said measurer in the same direction.
134. In a pulling over machine, pulling over means, a tip measurer, means to move said pulling over means longitudinally of the shoe for varying lengths of tip, and means controlled by the movement of said pulling over means for moving said measurer in the same direction.
135. A pulling over machine comprising a plurality of pairs of gripper jaws arranged adjacent the last and provision for closing all of said pairs of jaws simultaneously until the upper is gripped and thereafter continuing the closure of a portion only of said pairs of jaws to exert further pressure on a selected portion of the upper.
136. A pulling over machine comprising a plurality of pairs of gripper jaws arranged adjacent the last and provision under control of the operative for closing all of said pairs of jaws simultaneously until the upper is gripped and thereafter continuing the closure of a portion only of said pairs of jaws to exert further pressure on a selected portion of the upper.
137. A pulling over machine comprising a plurality of pairs of gripper jaws, separate devices for closing each pair of jaws, an actuator for said devices, and a yieldable member arranged in the line of stress of a portion only of said devices.
138. A pulling over machine comprising sets of toe and side grippers, closing means for each set of grippers including a push rod, means for actuating all of said rods simultaneously, and a yieldable member between said actuating means and a portion only of said push rods.
139. A pulling over machine comprising a plurality of pairs of gripper jaws, closing means for each pair of jaws, a movably mounted main table, an auxiliary table, yieldingly sustained by the main table, a separate push rod for actuating each jaw closing means, a portion thereof engaging the main table and a portion thereof engaging the auxiliary table, and means for moving said table to actuate the jaw closing means.
140. A pulling over machine comprising sets of toe and side grippers, and provision for exerting pressure on the upper through all of said grippers simultaneously for a time and thereafter greater pressure through a portion only of said grippers.
141. In a pulling over machine, means for supporting a shoe, sole downward, devices for seizing and pulling over the upper, and holding said shoe from upward movement, and means for inserting a fastener through the upper and into the tread face of the sole while the shoe is so supported and held by said devices.
142. In a pulling over machine, means for supporting a shoe, sole downward, devices for seizing and pulling over the upper and holding said shoe from upward movement, means for inserting a fastener into the sole while the shoe is so supported and held, and means for thereafter releasing the holding means.
143. In a pulling over machine, a driver constructed to engage a fastener and hold it in inserting position, inserting mechanism, and means for seizing the upper and pulling it over the last constructed and arranged to guide the fastener in its movement toward the shoe.
144. In a pulling over machine, a driver constructed to engage a fastener, means for moving said driver and fastener to a position for insertion upwardly, inserting mechanism, and means for seizing the upper and pulling it over the last constructed and arranged to guide the fastener in its upward movement.
145. In a pulling over machine, last supporting means, and means located at that side of the plane of the bottom of the last on which the body of the last is situated for placing an upper about the last and for stretching the upper prior to placing the upper against the edge of the last.
146. A pulling over machine comprising means for supporting a shoe with the tip line in full view of the operative, pulling over means, fastener inserting devices sustained thereby, and automatic means for actuating said devices to insert a fastener into the shoe.
147. In a pulling over machine, means for supporting a shoe with the tip line in full view of the operative, combined pulling over and fastener inserting devices, and common actuating means therefor.
148. In a pulling over machine, means for supporting a shoe with the tip line in full view of the operative, combined pulling over and fastener inserting devices, common

- means for actuating said devices to place an upper about a last and the inserting device in fastener driving position, and separate means for actuating said inserting device to 5 drive a fastener.
149. In a pulling over machine, means for supporting a shoe with the tip line in full view of the operative, combined pulling over and fastener inserting pulling over device, 10 means for actuating said pulling over device to place an upper about a last and adjacent its bottom and means controlled by the movement of said pulling over device for thereafter actuating said inserting device to 15 drive a fastener.
150. A pulling over machine comprising pulling over means constructed and arranged to receive the upper while extending loosely in assembled position over the top 20 of the forepart of the last with the edge at that side of the plane of the bottom of the last on which the body of the last is situated, and operating means for said pulling over means to carry the margin of the upper from 25 its position above to a position below the plane of the bottom of the last.
151. A pulling over machine comprising pulling over means arranged about the shoe and extending in a plane substantially parallel to the plane of the shoe bottom whereby the upper may be seized before being placed in contact with the last. 30
152. In a pulling over machine, a positioning device for engaging the last and extending above its tread face, means for placing an upper about the last, and means for changing the relative position of said device and last before the completion of the overplacing operation. 35
153. A pulling-over machine comprising means for pulling the upper over the last, and securing means adapted for securing the pulled over upper to the insole, in combination with means to support said last with its 40 bottom down in a plane at an angle to the horizontal and with the toe pointing upwardly toward the rear of the machine, whereby the fore part of the upper on said last is made observable to the workman similarly to viewing it upon the foot. 50
154. A pulling-over machine comprising means for pulling the upper over the last, and securing means adapted for securing the pulled over upper to the insole, in combination 55 with means to support the assembled shoe with its toe pointing in a direction of non-intersection with the plane of the front of the machine and with the tip line in full view of the operative as he stands in working position at the machine. 60
155. A pulling over machine comprising in combination means relatively to move the upper and last lengthwise in a plane substantially parallel to the plane of the bottom 65 of the last including a plurality of grippers at the end of the toe of the last, and means thereafter to move said grippers about the edge of the last to overplace the upper upon the last.
156. In a pulling-over machine, pulling over means on opposite sides of the last, and a single means independent of the actuator for the pulling-over means for maintaining all of said pulling-over means in uniform relation with the edge of the last whatever 70 the size or style of shoe being operated upon. 75
157. In a pulling-over machine, shoe supporting means, a device to engage the last, means for moving said device in a direction to carry the last heelward, and means for 80 thereafter withdrawing said device from engagement with the last. 85
158. A pulling-over machine comprising, in combination, means for supporting a last sole downward, pulling-over devices, actuating means to cause said devices to stretch the upper outwardly with relation to the bottom of the last, and means for actuating said devices to thereafter lay the stretched upper about the last. 90
159. A pulling-over machine comprising, in combination, means for supporting a last, pulling-over devices around the toe of the last, manual means to operate said devices to stretch the upper, and power operated 95 means to thereafter cause said devices to lay the stretched upper about the last into contact with the insole. 100
160. A pulling-over machine comprising, in combination, means for supporting a last, sole downward, pulling-over devices, actuating means to cause said devices to stretch the upper, means for actuating said devices to thereafter lay the stretched upper about the last, and means for inserting fastenings 105 upwardly through the upper and into the insole while so supported. 110
161. A pulling-over machine comprising, in combination, means for supporting a last, sole downward, pulling-over devices, manually operable means to cause relative movement of said devices and the last to stretch the upper, power operated means to thereafter cause said devices to lay the stretched upper about the last, and means for inserting fastenings 115 upwardly into the pulled-over upper. 120
162. A pulling-over machine comprising, in combination, means for supporting a last, sole downward, grippers for pulling the upper at the sides of the toe, manual means constructed and arranged to enable the operative to effectively control a gradual stretching of the upper by said side grippers, and power operated means under manual control for thereafter causing the grippers to lay the upper about the last and to secure the upper in pulled-over position. 125
163. A pulling-over machine comprising, in combination, means for supporting a last, 130

grippers arranged about the toe of the last for engaging the upper, treadle-operated means for relatively moving the last and grippers to stretch the upper, and power-actuated means to thereafter cause the grippers to lay the stretched upper about the last.

164. A pulling-over machine comprising, in combination, means for supporting a last, 10 grippers for engaging the upper, treadle-operated means for relatively moving the last and grippers to stretch the upper, power-actuated means to thereafter cause the grippers to lay the stretched upper 15 about the last, and automatic means for securing the upper in pulled-over position.

165. A pulling-over machine comprising, in combination, grippers for engaging the upper, manual means for causing the grippers to stretch the upper, automatic means to thereafter cause the grippers to lay the upper about the last, a driver arranged for movement with the grippers, and means to actuate the driver automatically to drive 25 a fastening through the pulled-over upper.

166. A machine of the class described having, in combination, pulling-over means, means for driving tacks at the opposite sides of a shoe and at the toe end, the tack 30 driving means at the toe being adjustable laterally of the shoe for right and left shoes.

167. A machine of the class described having, in combination, pulling-over means, tackers arranged at opposite sides of and 35 at the toe end of the shoe, each of said tackers being movable inwardly to tacking position over the shoe bottom, and means for shifting a plurality of tackers together transversely of the direction of said inward 40 movement to change the relation of the tacks inserted by them to the tacks inserted by the other tackers.

168. A pulling-over machine having, in combination, a toe tacker and a toe gripper, 45 said tacker and gripper being adjustable transversely of the machine to positions for operating on right and left lasts.

169. A machine of the class described having, in combination, grippers formed and 50 arranged to seize an upper throughout substantially the full width of the fore part of the shoe, and means for relatively actuating the grippers and last lengthwise of the shoe to tension the vamp forwardly and the adjacent portions of the quarters lengthwise of 55 the last and to hold the upper under tension in such position that the tensioned portion of the upper may be secured.

170. In a machine of the class described, 60 the combination with means for supporting a last, of grippers for engaging the upper at the toe of the last, and means for manually moving the toe grippers transversely laterally of the last in a curve around the toe.

171. In a machine of the class described,

the combination with means for supporting a last, of grippers for engaging the upper at the opposite sides of the last and at the toe of the last, and means for moving the toe gripper laterally of the last.

70

172. A machine of the class described having grippers positioned to engage an upper at opposite sides of a shoe, and a gripper positioned to engage an upper at the toe of the shoe and arranged for movement laterally 75 of the shoe, combined with means for relatively actuating the grippers and the last to strain the upper, and means for actuating the toe gripper laterally of the shoe.

173. A pulling-over machine comprising, 80 in combination, a rest for the shoe bottom, side and end pulling-over means, means for moving the end pulling-over means transversely, and means for moving the side pulling-over means longitudinally of the shoe 85 at an angle to the median line of the shoe.

174. A pulling-over machine, comprising in combination, means for supporting a last, pulling-over means, manually operable devices for causing the pulling-over means to 90 stretch the upper, a lock for said devices, a trip for said lock, and power operated means to cause the pulling-over means to lay the upper about the last.

175. A pulling-over machine having, in 95 combination, pulling-over means comprising grippers for gripping the upper, fastener-inserting means, a source of fastener supply, means movable for conveying a fastener from said source of supply into driving position relatively to the pulled-over shoe stock, and means controlled by the movement of the conveying means for presenting fasteners to the conveying means from the source of supply.

100

176. A pulling-over machine having, in combination, pulling-over means comprising grippers for engaging the upper positively, fastener-inserting means, a source of fastener supply, means for selecting fasteners from said source of supply, and means for engaging a selected fastener and conveying it into driving relation to the pulled-over shoe.

105

177. A pulling-over machine having, in 115 combination, pulling-over means, fastener-inserting means, a source of fastener supply, means for selecting fasteners from said source of supply, and means for engaging a selected fastener and conveying it into driving relation to the pulled-over shoe, the action of both the selecting means and the conveying means being controlled by the pulling-over means.

120

178. A pulling-over machine having, in 125 combination, grippers for seizing an upper and pulling it over a last, a bottom rest for the last for supporting the last sole-downward, and means for inserting a fastener adjacent to said grippers upwardly through 130

the upper into the shoe bottom, said grippers being constructed and arranged to form a guide to direct the fastener in its movement.

179. A pulling-over machine having, in combination, grippers for seizing and pulling an upper and wrapping it around the last, means for securing the pulled-over upper, and power operated mechanism for the grippers and the securing means timed and arranged to cause said means to secure the upper while the grippers continue to hold the upper.

180. In a machine of the class described, last holding means, a plurality of pairs of gripper jaws arranged about the last with their gripping surfaces lying in substantially the same plane prior to the upper stretching operation, and means for relatively actuating the grippers and the last to stretch the upper and then to infold the last in the upper.

181. In a machine of the class described, last holding means, a plurality of pairs of gripper jaws arranged about the last with their gripping surfaces lying in substantially the same plane prior to the upper stretching operation, means for relatively actuating the grippers and the last to effect stretching of the upper in substantially the plane of the top face of the last, and means for relatively actuating said grippers and the last to wrap the edge of the stretched upper toward the plane of the bottom face of the last.

182. In a machine of the class described, last holding means, means for stretching the upper in a plane relatively to the top face of the last to encounter substantially no friction of the upper against said top face of the last, and means for then actuating the last and the stretching means relatively to wrap the stretched upper about the last.

183. In a machine of the class described, last holding means, upper stretching means located during the initial stretching on the same side of the plane of the insole as is the top curved portion of the last and acting outwardly from the last whereby to reduce frictional resistance of the last to the stretching of the mid portions of the upper, and mechanism to actuate the last and the said means relatively first to stretch the upper and then to infold the curved top portion of the last in it.

184. A pulling-over machine having, in combination, toe and side grippers, a last bottom rest, and operating means arranged to permit all of the grippers to be closed and to be locked closed prior to stretching movement and then to permit the last and the grippers to be moved relatively longitudinally of the last to stretch the upper lengthwise prior to tightening the upper transversely by the side grippers and also

to be moved to stretch the upper transversely after it has been so foredrawn.

185. A pulling-over machine having, in combination, a last support, a plurality of grippers for pulling an upper over the last, and operating mechanism therefor including means by which a gripper can be moved while it holds the upper, about an axis extending substantially perpendicular to the plane of the shoe bottom to position the gripper with its gripping faces parallel to the side edge of the last.

186. In a pulling-over machine the combination with a last support and a toe gripper, of means for effecting relative adjustment of the toe gripper and the last in a direction transverse of the last bottom.

187. In a pulling-over machine the combination with a last support and grippers located at opposite sides of the last which is positioned against said support and capable of angular adjustment relatively to the center line of the machine into parallelism with the respectively adjacent side edges of the last, of means for effecting the pulling over operation, and means for effecting said adjustment prior to the pulling over operation.

188. A pulling-over machine having, in combination, grippers located on opposite sides of the last, means for relatively moving the grippers and the last for straining the upper about the last, means for actuating the grippers to effect overdrawing of the upper, gripper guides for controlling the direction of overdrawing movement, and means for adjusting said guides to vary that direction.

189. A pulling-over machine having, in combination, grippers located on opposite sides of the last, means for relatively moving the grippers and the last for straining the upper, and mechanism which can be adjusted to change the angular relation of the grippers to bring them into upper receiving positions parallel with the sides of differently shaped lasts.

190. A pulling-over machine having, in combination, side grippers, means for closing and moving the grippers to seize and pull the upper and to carry the edge of the upper into position to be fastened to an insole on the last bottom, and means connected with both side grippers and arranged for adjustment to change simultaneously the angular relation of both side grippers to the center line of the last.

191. In a pulling-over machine, a last bottom rest, gripping means located at the opposite sides of the shoe and constructed and arranged relatively to said bottom rest to present their gripping faces in upper receiving position substantially parallel with the plane of the forepart of the last bottom and to move outwardly from the last substantially in that plane to stretch the upper.

transversely of the last prior to its being wrapped around the last by relative movement of the gripping means and the last at an angle to that plane, and operating mechanism for effecting the relative movements of said parts to do their work.

192. In a pulling-over machine, a last bottom rest, gripping means located at the toe of the shoe and constructed and arranged relatively to said bottom rest to present gripping faces in an upper receiving position substantially parallel with the plane of the forepart of the last bottom and to pull outwardly relatively to the last substantially in that plane to stretch the upper longitudinally prior to its being wrapped around the last, and means for relatively actuating said parts to seize and to pull the upper and thereafter to bend the upper over for conforming it to the top face of the last at the toe.

193. In a pulling-over machine, a plurality of grippers arranged to engage the toe tip of a shoe, operating means for actuating said grippers and the last relatively to stretch the tip lengthwise and means for thereafter actuating the said grippers relatively to one another laterally to stretch the tip transversely.

194. In a pulling-over machine, the combination of positioning means to engage the toe end of a last and the heel portion of the upper about the last, means for drawing the upper toward while so positioned, grippers to engage the upper at the forepart to stretch the upper transversely, and means permitting relative transverse movement of the toe and heel portions of the positioning means in accordance with the swing of the last.

195. A pulling-over machine, having in combination, shoe positioning means comprising a toe engaging member and a heel part engaging member, means normally acting in a direction to cause relative approach of said members, pulling-over means located between said members, and means for adjustment of one of said members transversely with respect to the pulling-over means in accordance with the swing of the last.

196. A pulling-over machine, having in combination, a toe positioning stop, a heel part engaging member, and a sole engaging member, and pulling-over means at the sides of a last positioned by said parts, said heel part engaging member being movable transversely with respect to the pulling-over means to position rights and lefts.

197. A pulling-over machine, having in combination, a heel support comprising shoe engaging arms, said arms being constructed and arranged to have united movement in two directions for adjustment to lasts of different sizes and swing, and relative move-

ment to receive the heel portion of the last between them, pulling-over means at the sides of the last held by the heel support, and means for causing the pulling-over means to draw the upper to the last while so held.

198. A pulling-over machine, having in combination, a toe rest to limit the toward movement of a last in the machine, a heel member held under yielding pressure toward said rest and having arms engaging the counter portion of the upper, means for pressing the arms toward each other, pulling-over means at the side of the last intermediate the toe rest and heel member, and means for causing the pulling-over means to lay the upper to the last.

199. A pulling-over machine having in combination, a toe rest or stop to limit the toward movement of a last in the machine, means acting to relatively move the upper and last longitudinally to position the upper on the last, and pulling-over means at the sides of the last to draw the upper to the last.

200. A pulling-over machine, having in combination, means for overworking an upper, a sole rest, and means for disengaging the sole rest from the shoe sole while said overworking means is in engagement with the upper.

201. A machine of the character described, having in combination, means for overworking an upper, a sole rest, means for moving the sole rest in a direction longitudinally of the shoe, and means for disengaging the sole rest from the shoe sole while said overworking means is in engagement with the upper.

202. A machine of the character described, the combination of means for overworking an upper, a sole rest, and means for moving the sole rest away from the edge of the sole while said overworking means is in engagement with the upper.

203. A machine of the character described, the combination of means for overworking an upper, a sole rest, means for moving the sole rest away from the edge of the sole while said overworking means is in engagement with the upper, and means for securing the upper to the insole.

204. A machine of the character described, the combination of means for overworking an upper, a sole rest and a toe positioning stop, and means for moving the sole rest and toe positioning stop from operative position while the overworking means is in engagement with the upper.

205. In a pulling-over machine, means acting upon the end of the toe portion of a last to limit the toward movement of the last, means acting upon the counter portion of an upper assembled on said last to conform the rear portion of the upper to the

last by a sliding shaping movement, and pulling-over means acting to lay the forepart of the upper to the wood of the last.

206. A pulling-over machine having in combination, a toe rest or stop, pulling-over means, and operating means to relatively move the last and upper longitudinally to draft the upper forwardly.

207. In a pulling-over machine, means acting upon the toe portion of a last to limit the toeward movement of the last, means acting upon the counter portion of an upper assembled on said last to conform the rear portion of the upper to the last by a sliding shaping movement as the last and upper are placed in the machine, and pulling-over means acting thereafter upon the upper at the forepart to lay the forepart of the upper to the wood of the last.

208. A pulling-over machine, having in combination, means for overworking an upper, a sole rest and toe stop, and means for actuating said toe stop downwardly and forwardly while the overworking means is in engagement with the upper.

209. A pulling-over machine having means for gripping the upper and pulling it over the forepart of a last, in combination with a toe stop and a heel rest, said heel rest having side arms which are self-adaptable to the curvature of the sides of the heel portion of a right or left last.

210. In a machine of the character described, means for engaging the counter portion of an upper on a last to conform the rear portion of the upper to the last by a sliding shaping movement relative to the last and upper, means for engaging the forepart of the upper to draw it to the wood of the last at the forepart, and means for fastening the upper in the position to which it has been thus drawn.

211. In a machine of the character described, means laterally movable to accommodate itself to lasts of different swing and

constructed for engaging the counter portion of an upper on a last to conform the rear portion of the upper including the forward ends of the counter to the last by a sliding shaping movement relative to the last and upper, means for engaging the forepart of the upper to draw it to the wood of the last at the forepart, and means for fastening the upper in the position to which it has been thus drawn.

212. In a pulling-over machine, grippers for engaging and placing an upper about a last, a last support, provisions for relatively adjusting said grippers and last support in a direction longitudinally of the last, and provisions for relatively adjusting the last with respect to and for the action of the grippers in placing the upper about the last.

213. In a pulling-over machine, a shoe positioning device comprising a heel seat and shoe engaging arms, said parts being constructed and arranged to have united movement in one direction and relative movement in another direction, pulling-over means at the forepart of the last positioned by said support, and means for causing the pulling-over means to place the upper about the last while positioned by said device.

214. In a pulling-over machine, pulling-over means, a shoe positioning device comprising a heel seat, shoe engaging arms mounted on said heel seat to position the heel portion of the upper upon the last as the parts are placed in the machine, and means for actuating the pulling-over means to lay the upper at the forepart to the wood of the last while held by said device.

In testimony whereof, I have signed my name to this specification, in the presence of two subscribing witnesses.

WILLIAM C. STEWART.
